SLUG CASTING MACHINE

James C. Plastaras, Laurelton, N. Y., assignor to
Mergenthaler Linotype Company, a corpora-
tion of New York

Application September 5, 1940, Serial No. 355,434

155 Claims. (Cl. 199—47)

This invention relates to slug casting machines wherein an assembled line of matrices is presented to the face of a slotted mold, the mold filled with molten metal to form a type bar or slug against the matrices which produce the type characters thereon, and the type bar or slug thereafter ejected from the mold, trimmed and stacked in a galley located at the front of the machine.

While the instant improvements deal more specifically with the slug casting mechanism per se, they constitute part of a complete machine which is substantially new in its entirety and which has been designed chiefly for economy in cost of construction, greater capacity, and increased flexibility of operation.

Thus, instead of the usual four molds with which the commercial machines are equipped, the improved machine provides for a selection of eight different molds, and indeed the arrangement is such that even a greater number of molds could be employed if desired. Furthermore, the changing from one mold to another is accomplished by power operated mechanism through controls located at the front of the machine within easy reach of the operator. Then, too, other adjustments which must accompany the substitution of one mold for another, as for instance, the adjustment of the ejector blade width to correspond with the slot length of the selected mold, and the adjustment in the spacing of the trimming knives to correspond with the slot width of the selected mold, are effected automatically and by power as the substitution of molds is made.

To be more specific, the active mold is located and clamped in a mold holder which in its normal position, i. e., the slug ejecting position, is vertically disposed. The mold holder carries but a single mold and is adapted, during a machine cycle of operation, to swing upwardly from its normal vertical position into a horizontal casting position and then move forwardly and backwardly into and out of contact with the composed line before and after casting, respectively. After the casting operation, the base of the slug is trimmed by a stationary knife having a cutting edge long enough to accommodate the longest slug to be cast and which is located so that the slug is pushed laterally past it as the mold moves downwardly from casting to ejecting position. In the latter position, the ejector blade moves forwardly to push the slug out of the mold and between a pair of spaced trimming knives that shave the side faces of the slug to bring it to

proper point size. After the slug has been ejected, the ejector blade moves rearwardly to its normal position of rest, whereupon the machine is ready for the next casting cycle. Here, it may be stated that two wiping mechanisms are provided, one for cleaning the front and rear faces of the mold adjacent the mold slot, and the other for removing any shavings adhering to the trimming knives, as the mold is swung from and to its normal ejecting position.

The machine is equipped with a series of molds vertically disposed in individual pockets of a mold magazine located directly beneath the mold holder when the latter is in its normal position. The pockets of the magazine are open at the top and bottom, and the magazine is arranged to be moved in a fore-and-aft direction to bring any selected mold into alignment with the mold holder. The molds are transferred from the magazine to the mold holder and vice versa by a vertically reciprocable transfer slide. Normally, this slide extends upwardly through the pocket allocated to the active mold then positioned in the mold holder and is locked in that raised position so long as said mold remains in use, the slide in turn locking the magazine against further adjustment or any movement tending to destroy the alignment between the mold holder and the magazine pocket.

To substitute a different mold for the one in use, all that is required of the operator is to move a control handle from one position to another, adjust the mold magazine by a selecting lever to a position corresponding to the desired mold, and then return the control handle to its original or normal position. The first movement of the control handle accomplishes three operations, first, it renders inactive the devices that locate and clamp the mold in the mold holder, second, it unlocks the mold transfer slide, and third it controls power mechanism that pulls the active mold out of the mold holder down into its proper pocket in the mold magazine. When the transfer slide has restored the mold to the magazine, it is located beneath and clear of the magazine, which can then be adjusted to select a different mold for use. Thereupon, with the aid of an indicator, the operator moves the mold selecting lever to a position corresponding to the newly selected mold. That movement of the selecting lever adjusts the magazine to a position wherein the newly selected mold is brought into alignment with the mold holder at the top and with the transfer slide at the bottom. Now, the operator restores the control handle to its original posi-

Mold and mold holder

As shown in Figs. 1, 26, 27 and 28, the slotted molds A, with which the machine is equipped, consist each of a base portion A¹, a cap portion A², and intermediate end sections or liners A³, A⁴. These portions of the mold are clamped together by machine screws passing through the cap and liners at the ends and threaded into the base portion. The base and cap portions of the mold are formed with tongues A⁵ and A⁶ arranged to fit into opposed grooves B¹ and B² formed in a mold holder B. Each mold is further equipped with end plates A⁷ and A⁸ fitting into aligned grooves formed in the cap and body portions of the mold at the opposite ends thereof, and being held in place by screws passing through the plates and threaded endwise into the mold body portion (Fig. 8). The plates extend beyond the ends of the mold for reasons later to appear. At their opposite ends, the plates A⁷ and A⁸ extend into the opposed grooves B¹ and B² of the mold holder, the ends of the plates engaging the bottoms of the grooves. The fit is a close one, although sufficient tolerance is provided to permit the mold to be slid endwise into and out of the holder. The edge of the tongue A⁶ on the base of the mold likewise engages the bottom of the groove B². As to the tongue A⁵ on the cap of the mold, however, its edge will be spaced from the bottom of the groove B¹ a distance which will vary depending upon the thickness of the mold liners. Actually the chief purpose of the tongues A⁵ and A⁶ is to conduct heat from the mold to the mold holder from whence it is dissipated. The mold liners A³ and A⁴ are slotted to receive the end plates, which thus act with the clamping screws to prevent displacement of the liners.

The mold holder B (Figs. 26, 27 and 28) comprises two side portions B³ and B⁴ spaced apart to receive the mold and wherein are located the oppositely disposed mold retaining grooves B¹ and B² previously referred to. The side portions are interconnected at the bottom by an end portion B⁵ formed integrally therewith but offset rearwardly, as shown in Fig. 27, so as to permit the mold to be slid endwise into and out of the holder without interference. The side portions of the mold holder are also interconnected at the top by a head portion B⁶ likewise formed integrally therewith. The mold holder is fastened at the front end of a fore-and-aft hollow rock shaft B⁷, as by screws b passing through the head portion B⁶. The rock shaft is mounted in the machine for rotation through an angle of 90° so as to swing the mold holder, and consequently the mold, from a vertical or slug ejecting position into a horizontal or slug casting position, and return, at each casting cycle.

The mold A is located and locked endwise in the mold holder B (Figs. 26 and 27) by a stop screw X, threaded upwardly into the mold head portion B⁶ at its bottom edge and against which the mold banks at its upper end, and also by a latch B⁸ located at the rear of the mold holder and pivotally mounted at the lower end of a bracket B⁹. The portion of the bracket on which

the latch is mounted underlies the head of the mold holder, although the bracket itself is secured to the mold holder at the front by a pair of vertically spaced screw and slot connections B¹⁰. The latch B⁸ is formed with a portion extending below its pivotal mounting and terminating in a projecting nose B¹¹ arranged to engage in a recess A⁹ formed in the rear face of the mold end plate A⁷ which is located adjacent the head portion of the mold holder. The nose B¹¹ of the latch B⁸, is held in the recess A⁹ by spring tension. Thus, the mold is locked in the holder against endwise movement in one direction by the stop screw X and in the opposite direction by the latch B⁸. Accuracy in the endwise positioning of the mold in the holder is secured by adjusting the setting of the stop screw which is provided with a lock nut X¹ for maintaining its adjustment and also by adjusting the bracket B⁹ on which the latch B⁸ is mounted in a vertical direction. The adjustment of the bracket B⁹ is permitted by the screw and slot connections B¹⁰ and is determined by a pair of adjusting screws B¹² and B¹³, the former being threaded downwardly through a portion of the bracket overlying the holder, and the latter upwardly through the portion of the bracket underlying the holder head portion, both screws engaging against adjacent surfaces of the mold holder head. A spring buffer X² is located in the head of the mold holder in a position to engage the upper edge of the mold end plate A⁷, its purpose being to ease the mold gently against the stop X as it is slid endwise into the mold holder (Fig. 26).

The mold A is located sidewise in the mold holder by the mold end plates A⁷ and A⁸ which, as previously stated, extend into the grooves B¹ and B², having a close sliding fit with the bottoms thereof. The clearance necessary to permit sliding is taken up by a cam B¹⁴ pivotally mounted in the right side member B³ of the mold holder and formed in two parts, one located adjacent the rear and the other adjacent the front face of the holder (Figs. 26 and 28). The cam parts are screwed together so as to act as a unit, the active edges thereof in the normal position of the cam unit being arranged to engage the outer edge of the mold cap A², at the base of the tongue portion A⁵ thereon, and wedge the mold tightly against the left side portion B⁴ of the mold holder so as to locate and lock the mold tightly in place therein.

The manner in which the latch B⁸ and the cams B¹⁴ are operated during the substitution of one mold for another is described later on.

To complete the description of the mold holder, it is pointed out that provision is made for water-cooling the mold. The inlet and outlet water ducts pass longitudinally through the hollow rock shaft B⁷ (Figs. 26 and 27). The water circulates around the mold through passageways formed in the mold holder and which may be traced from an inlet port W through a horizontal passageway W¹, downwardly through a vertical passageway W² in the right side portion B³ of the holder, then through a horizontal passageway W³ in the bottom mold portion B⁵ to another vertical passageway W⁴ in the left side portion B⁴ of the holder, and finally to an outlet port W⁵ through another horizontal passageway W⁶ in the mold holder head. Since the water ducts passing through the rock shaft will rotate with the latter, suitable flexible connections permitting such movement will be made with the source of water supply.

Mold holder operating mechanism

During a machine cycle of operation, the mold holder B is swung from the normal vertical position shown in Fig. 1 upwardly to the right to bring the mold into a horizontal casting position, whereupon the mold is moved forwardly into contact with the composed line to close the mold at the front, then after the slug is cast moved rearwardly away from the composed line, and finally swung downwardly to its normal position for the ejection of the cast slug. The normal position of the mold holder is determined by a fixed stop T against which the holder banks at the left (see Fig. 1).

The various movements of the mold holder B above mentioned are brought about by corresponding movements of the hollow rock shaft B⁷ on which it is mounted. Thus (see Figs. 2 and 3), the hollow rock shaft is rotatably mounted in a pair of fixed bearings, one designated C located near the front of the rock shaft and the other designated C¹ just rearwardly of its center. At its front end, the hollow shaft is formed with two segmental flanges B¹⁵, B¹⁶ (Figs. 1, 3 and 26) located, one at the top, and the other at the bottom, in diametrically opposed relation and spaced equally about the vertical center line of the shaft. During the rotational movement of the rock shaft, the flanges B¹⁵ and B¹⁶ seat in a recess formed in the face of the front bearing C, where they are retained by a pair of segmental gibs C², C³ fastened to the bearing at its front face and which likewise are arranged in diametrically opposed relation, the gib C² at the top, however, being offset to the left of said vertical center line, and the lower gib C³ to the right. The relative locations of the gibs C², C³ and the segmental flanges B¹⁵, B¹⁶ are such that, when the mold holder is in its normal position, and throughout substantially its full upward swinging movement to bring the mold into casting position, the gibs cooperate with the segmental flanges to hold the rock shaft, and consequently the mold holder, against forward movement. However, when the mold holder arrives in the horizontal casting position, the segmental flanges B¹⁵ and B¹⁶ stand clear of the gibs C², C³ (see the dotted line position shown in Fig. 1), with the result that the rock shaft is free to be moved axially in effecting the forward and rearward movements of the mold into and out of contacting relation with the composed line.

The power for rotating the hollow rock shaft B⁷ to swing the mold holder from ejecting to casting position is derived from the main cam shaft M (Figs. 18 and 19) which is disposed in a fore-and-aft direction and rotated once during each casting cycle. However, the power for rotating the rock shaft in the reverse direction, i. e., to swing the mold holder from casting to ejecting position, is pneumatic, although the operation is under the control of the same cam through which the initial swinging movement is effected.

The operating mechanism, as best shown in Figs. 3 and 24, includes a rocker arm B¹⁷ fulcrumed near its center on a fixed portion of the machine frame and formed at its upper end with a gear sector B¹⁸ meshing with gear teeth B¹⁹ formed around a portion of the periphery of the rock shaft B⁷ at the rear end thereof. At its lower end, the rocker arm is equipped with an antifriction roller B²⁰ arranged to track along an edge cam M¹ keyed to the main cam shaft M.

When the parts are in their normal positions corresponding to the slug ejecting position of the mold, as shown by the full lines in Fig. 24, the cam follower B²⁰ just clears a low concentric portion of the cam M¹. Upon the inauguration of the casting cycle, however, the cam shaft M rotates in the direction of the arrow, whereupon the cam M¹ picks up the cam follower B²⁰ which rides to a high concentric portion of the cam M¹, causing the rocker arm B¹⁷ to swing in a clockwise direction to the position shown by the dotted lines in Fig. 24. That movement of the rocker arm rotates the hollow rock shaft B⁷ through an angle of 90° to bring the mold holder into its horizontal casting position. During the engagement of the cam follower B²⁰ with the high portion of the cam M¹, those operations incidental to the actual casting of the slug take place, i. e., the mold is moved forwardly into contact with the composed line, the slug cast, and the mold then moved rearwardly out of contact with the composed line. Thereafter, the mold holder is swung downwardly to its normal vertical position for the ejection of the cast slug.

This downward or restoring movement of the mold holder is effected through a pneumatically operated mechanism (best shown in Fig. 24), including a cylinder B²¹ and a one-way acting piston B²² arranged for reciprocation therein. A piston rod B²³ extends through the cylinder head and is connected at its outer end by means of a swivel joint B to the rocker arm B¹⁷ at the upper end thereof. Through an air line and an automatically controlled air valve later to be described, the cylinder, at the end opposite that through which the piston extends, is vented to the atmosphere during one stage of the machine cycle and connected to a source of air pressure during another stage of the machine cycle. Thus, during the period the cam follower B²⁰ rides from the smaller concentric portion of the cam M¹ to the higher concentric portion thereof, the cylinder is vented so that no air resistance is offered to the rocker arm as it moves to swing the mold holder up to the casting level. Later on, however, and while the cam follower is still upon the high portion of the cam, the cylinder is connected to the source of air pressure. Consequently, when the drop in the cam arrives opposite the cam follower, the rocker arm B¹⁷ is restored to its normal position by the action of the air pressure upon the piston B²² but under the restraining influence or control of the cam M¹. The swinging movement of the rocker arm B¹⁷ entails a slight swinging movement of the piston and cylinder mechanism, and for this reason the cylinder B²¹ is pivotally mounted on a fixed portion of the machine frame, as at B²⁵ (see Fig. 39).

As the mold holder swings down to its normal or slug ejecting position, the cam roller B²⁰ follows the incline of the cam M¹ between the high and the low concentric portions thereof. However, when the mold holder is arrested in its normal or slug ejecting position by banking against the fixed stop T, the cam roller leaves the cam so that there is some clearance between the low concentric portion thereof and the cam roller (Fig. 24). This clearance permits a relative adjustment of the cam roller with respect to the rocker arm B¹⁷ on which it is mounted, the adjustment being for the purpose of insuring the proper location of the mold when at the horizontal casting level and when it is in its vertical or slug ejecting position. To this end (see Fig. 24),

the roller B^{20} is carried at the lower end of an arm B^{26} pivotally mounted at its upper end, as at B^{27} , on the rocker arm B^{17} just below the fulcrum point thereof. The clearance, previously mentioned, permits sufficient relative adjustment of the arms B^{17} and B^{26} about the pivot B^{27} to insure that the mold will be properly located when in casting position. The degree of adjustment is regulated by a set screw B^{28} threaded through the rocker arm B^{17} into banking engagement with the roller carrying arm B^{26} and is maintained by a screw B^{29} passing through the rocker arm just below the set screw and threaded into the arm B^{26} .

As previously stated, when the mold holder B occupies its horizontal casting position, it is first moved forwardly to bring the mold A into engagement with the composed line and then, after the slug has been cast, moved rearwardly so that it may be restored to its normal vertical position. Such forward and rearward movements of the mold holder B are effected through corresponding movements of the hollow rock shaft B^7 on which it is mounted, the mechanism employed (as best illustrated in Figs. 3 and 32), being actuated from the main cam shaft M and including a rocker arm D fulcrummed near its center for rocking movement in a fore-and-aft vertical plane. At its lower end, the rocker arm is provided with an antifriction roller D^1 constrained to follow a cam track M^2 presented between two cam elements M^3 and M^4 splined to the shaft M (see also Fig. 19). The rocker arm D is bifurcated at its upper end (Figs. 3 and 32) so as to straddle a fore-and-aft rod D^2 located immediately below the hollow rock shaft B^7 . The bifurcated portion of the rocker arm D engages between a forward enlarged portion D^3 of the rod D^2 and a collar D^4 fixed to the rod at the rear of the arm. The enlarged portion D^3 is guided for fore-and-aft sliding movement in a fixed portion of the machine, whereas the collar D^4 banks against the front end of a housing D^5 through which the rod D^2 extends. Normally, the collar D^4 is held in engagement with the housing D^5 by a compression spring D^6 encircling the rod D^2 and which reacts between the front inner face of the housing, on the one hand, and a sleeve D^7 likewise encircling the rod and slidably arranged in the housing, on the other hand, the sleeve being buttressed by a second collar D^8 pinned to the rod at the rear end thereof. The housing D^5 , for the most part, is cylindrical in shape and is guided for fore-and-aft movement in an extension of the fixed bearing support C^1 for the rock shaft B^7 . At its rear end, however, the housing is formed with an enlarged flange portion D^9 extending upwardly to engage in an annular groove b^1 formed in the outer cylindrical surface of the hollow rock shaft B .

In the operation of the parts, after the mold holder B has been swung to its horizontal casting position, a portion of the cam track M^2 arrives opposite the roller D^1 , which portion is shaped so as to turn the rocker arm D in a clockwise direction looking at the machine from the left, as in Fig. 3, and actuate the rod D^2 in a forward direction. The forward movement of the rod D^2 is imparted to the housing D^5 through the compression spring D^6 , and consequently to the rock shaft B^7 , with the result that the mold holder is moved forwardly to bring the mold into engagement with the composed line. There is sufficient play between the collar D^8 , at the end

of the rod D^2 , and the housing D^5 to permit the spring D^6 to yield when the mold is brought in contact with the line. After the slug has been cast, and at the proper stage in the machine cycle, another portion of the cam track M^2 arrives opposite the roller D^1 , which portion is so shaped as to turn the rocker arm D in a counterclockwise direction back to normal position. This movement of the rocker arm acts, first, to take up whatever play was occasioned by the yielding of the spring D^6 and, then, positively to move the hollow rock shaft B^7 in a rearward direction back to its normal position through the housing D^5 and the rod collar D^4 which engages the housing directly. At this point, it might be stated that the front and rear faces of the bifurcated end portion of the rocker arm D are rounded off, where they engage the enlarged portion D^3 and the collar D^4 of the rod D^2 , in order to accommodate the forward and rearward movements of the latter. It might also be stated that the teeth B^{19} at the rear end of the rock shaft B^7 , and which are engaged by the gear sector B^{18} , are of sufficient length to accommodate the fore-and-aft movement of the rock shaft.

On occasion, it may be desirable to remove the mold holder B and its supporting rock shaft B^7 from the machine. To this end, provision is made for disengaging the housing flange D^9 from the groove b^1 so as to free the rock shaft for forward movement. As shown in Fig. 32, the flange D^9 is formed with an extension D^{10} having a pivotally mounted handle D^{11} at its outer end. The handle is formed with a latch portion D^{12} arranged to engage in a groove c presented by an extension of the shaft bearing support C^1 . The latch portion D^{12} is normally held in the groove c by a leaf spring D^{13} , screwed to the flange extension D^{10} and which engages a flat bottom face of the handle D^{11} . To effect disengagement of the latch D^{12} , all that is necessary is to withdraw the latch from the groove c by rotating the handle D^{11} against the action of the leaf spring D^{13} , whereupon the flange D^9 will be free to be swung downwardly to the dotted line position shown in Fig. 32 where it clears the groove b^1 in the rock shaft. Such swinging movement of the flange is permitted by the cylindrical form of the housing D^5 and the manner in which it is mounted. With the flange D^9 thus disengaged, the rock shaft B^7 and mold holder B may be drawn forwardly out of the machine, provided, of course, they are swung to clear the gibs C^2 and C^3 . During the normal operation of the machine, the latch D^{12} will slide back and forth in the groove c , the latter having sufficient length to accommodate the movement (see Fig. 25).

In order properly to level or locate the mold in its final horizontal slug casting position as it is moved forwardly into engagement with the composed line and to take up the play that may exist in the mold holder actuating mechanism, there is provided a locating lug C^4 (see Figs. 1, 29, 33 and 34) mounted on a fixed portion of the machine frame adjacent the right end of the mold holder when the latter is at the casting level. The lug C^4 is located in a position to clear the mold holder during its swinging movement, but when the mold holder is advanced to effect the engagement of the mold with the composed line, i. e., from the solid to the dotted line position shown in Figs. 33 and 34, the lug C^4 enters a notch B^{30} with which the mold holder is provided, the lug being tapered adjacent its rear face, as at C^5 , to facilitate its entry into the notch.

The lug C⁴ is formed as an integral portion of a block C⁶ tongued and grooved to a fixed portion of the machine frame and secured in position by a screw and slot connection C⁷. The connection C⁷ provides for a limited vertical adjustment of the locating lug, as determined by a pair of set screws C⁸ and C⁹ threaded, one downwardly and the other upwardly, through the block and into engagement with the screw forming part of said screw and slot connection (Fig. 29). Incidentally, it might be stated that the notch B³⁰ in the mold holder is sufficiently large to permit the mold holder to slide past the lug C⁴ when it is desired to remove the mold holder and rock shaft assembly from the machine.

Metal pot and pump

After the mold has been moved forwardly into engagement with the line, the metal pot U is likewise moved forwardly into engagement with the rear face of the mold, the lockup effected, and the mold filled with molten metal to produce the slug.

In the present machine, the metal pot U is mounted on a carriage U¹ supported in the machine frame and adapted for horizontal fore-and-aft movement into and out of casting relation with the mold. At its four corners, the carriage is equipped with rollers U² guided on rails presented by the channel members of the frame (see Fig. 39).

The reciprocation of the metal pot is effected by a cam M⁷ fixed to the main cam shaft M and formed in its peripheral surface with a grooved trackway adapted to receive a roller U³ journaled in the end of a short arm U⁴ of a bell crank lever U⁵ pivoted on the machine frame. A long arm U⁶ of the lever is connected to a rod U⁷ pivoted to one arm of a bell crank lever U⁸, the other arm of which is connected at one end of a toggle link U⁹ having its opposite end connected to a lug at the rear of the carriage U¹. The lever U⁹ is pivotally connected at the front end of a bolt U¹⁰ which extends through an opening in a fixed block U¹¹ and is held by a nut threaded on the end of said bolt. The arm U⁶ of the bell crank lever U⁵ is connected to the rod U⁷ by means of a link U¹² having spaced arms which present, at their upper ends, a collar U¹³ encircling the rod U⁷ and acting as an abutment for a relief spring U¹⁴ which reacts between the collar and a pair of adjusting lock nuts U¹⁵ threaded on the rod at its lower end. An adjustable wedge-shaped element U¹⁶ located between the block U¹¹, through which the bolt U¹⁰ extends, and a shoulder U¹⁷ presented by the bolt U¹⁰, permits locating the pivot point of the bell crank lever U⁵ in a position to insure a proper lockup between the mold, on the one hand, and between the front face of the mold and the composed line, on the other hand.

At the proper stage in the machine cycle, the cam M⁷ rocks the bell crank lever U⁵ to move from the position shown by the solid lines in Fig. 39 to the position shown by the dotted lines therein, with the result that the toggle formed by the link U⁹ and the arm of the bell crank lever U⁶ is partially straightened out, thus moving the metal pot forwardly into contact with the mold. Since the force tending to straighten out the toggle is exerted through the relief spring U¹⁴, it is apparent that any desired lockup pressure can be secured.

Metal is forced into the mold by a pump plunger

U¹⁸, the operation of which is controlled from a pair of cams M⁸ and M⁹ likewise mounted on the main cam shaft. The connections for this purpose are not shown nor will they be described herein since they, together with the metal pot operating mechanism, form the subject matter of a copending application Serial No. 269,833, filed April 25, 1939.

After the slug has been cast, the metal pot U is moved rearwardly as the cam M returns the bell crank lever U⁵ back to the solid line position shown in Fig. 39. The mold is then free to move rearwardly out of engagement with the composed line and back to its normal position for slug ejection.

Mold wiping device

As the mold holder is swung upwardly preparatory to the slug casting operation, suitable mechanism acts to wipe the front and rear faces of the mold in order to insure a tight lockup between the mold and the composed line at the front and between the mold and the mouthpiece of the metal pot at the rear. This mold wiping mechanism is best illustrated in Figs. 29, 30 and 31. It includes two spaced arms E and E¹ having pads E² and E³ secured at their upper ends and arranged to engage the front and rear faces of the mold A, respectively. The arms E and E¹ are arranged to be swung as a unit from their normal position, shown by the solid lines in Fig. 29, through an angle to the position shown by the dotted lines therein, simultaneously with the upward swinging of the mold A. The path through which the pads E² and E³ move during their swinging movement in conjunction with the swinging movement of the mold is such as to cause the pads to wipe the mold from one end of the mold slot to the other.

The arms E and E¹ at their lower ends are hinged, in spaced relation, to an arm E⁴ having a hub portion E⁵ rotatably mounted on a shaft projecting from a fixed portion of the machine frame. The hub portion E⁵ is formed at its rear end with a second arm E⁶ presenting an anti-friction roller E⁷ arranged to track along an edge cam M⁶ fastened to the main cam shaft M at the front end of the latter. The hinged arms E and E¹ are urged toward each other, and consequently toward the opposite faces of the mold, by a pair of springs E⁸ disposed adjacent the opposite lateral edges of said arms and tensioned between pins E⁹, mounted on a rearward extension of the back arm E¹, and similar pins E¹⁰ extending from the lateral edges of the front arm E. When the arms E, E¹ are in their normal positions, the pads E², E³ are separated to an extent sufficient to permit the mold to pass between them without interference, the degree of separation being determined by a fixed plate E¹¹ having wedge surfaces E¹² engaging the inner opposed faces of the arms E, E¹ (Fig. 31). However, when the arms E, E¹ swing to the right to perform their mold wiping function, they become disengaged from the wedge plate E¹¹, and move toward each other under the action of the springs E⁸ until the pads carried thereby engage the opposite faces of the mold. When the mold passes from between the pads, movement of the arms E, E¹ toward each other is arrested by the engagement of opposed banking screws E¹³ threaded, one through each of the arms E, E¹, with a post E¹⁴ located between said arms and formed integrally with the crank arm E⁴ on which said arms are hinged. When the banking

screws are properly adjusted, they space the arms so as to insure their proper engagement with the plate E¹¹ when they return to normal position.

As previously stated, the swinging movement of the arms E, E¹ is controlled by the cam follower E⁷ through its engagement with the edge cam M⁶, such engagement being maintained under the action of a tension spring E¹⁵ looped at one end through an eye formed in the post E¹⁴ and anchored at its opposite end to a fixed part of the machine. Such is the configuration of the cam M⁶ that, upon the inauguration of a machine cycle and after the mold A has reached the lowermost dot and dash line position shown in Fig. 29, where the mold slot at its left end is located between the pads E², E³, a drop in the cam will arrive opposite the follower E⁷, causing the arms E, E¹ to swing from the solid line to the rightmost dot and dash line position shown in that figure. During the same interval, the mold will move upwardly to the intermediate dot and dash line position so that, in consequence, the mold slot will be wiped over its entire length, remembering of course that as soon as the arms start to move, the pads are drawn inwardly by the springs E⁸ to engage the mold faces. Thereafter, the mold continues its upward movement to the horizontal casting level, whereas the arms return to their normal position as the cam follower again rides up onto a high portion of the cam. Upon their arrival in normal position, the arms are again pressed outwardly by the wedge surfaces E¹² of the fixed plate E¹¹ and consequently will be located in a position to clear the mold as the latter swings downwardly to vertical ejecting position after the slug has been cast.

Slug trimming knives

As the mold with the cast slug therein is swung downwardly to the vertical ejecting position, the bottom edge of the slug is trimmed by a stationary knife F which brings it to proper height (Figs. 21, 22 and 23). Considerable force is required to effect the shearing operation of the slug and this is one of the reasons for using pneumatic power in returning the mold holder to its normal or slug ejecting position.

The knife F is vertically disposed and is of sufficient length to accommodate the largest slug capable of being handled by the machine.

The cutting edge F¹ of the knife is disposed so that the shearing action on the slug will be progressive from one end thereof to the other, thereby conforming with good shearing practice. The knife edge F¹ is arranged for limited adjustment toward and away from the rear face of the mold, the knife for this purpose being mounted at an angle to the plane of movement of the mold. The mounting includes a pair of lugs F², F³ vertically spaced on a fixed portion of the machine frame and presenting inclined backing surfaces with which the knife is held in engagement by screw and slot connections F⁴. It will be apparent that a fore-and-aft adjustment of the knife edge, as limited by the screw and slot connection, can be obtained by a side-wise movement of the knife along the inclined lug supports, the adjustment being determined by a pair of banking screws F⁵ which engage the non-cutting edge of the knife. The banking screws are threaded into a fixed portion of the machine frame and are formed with heads provided with radially extending holes to facilitate

the adjustment. The adjusted positions of the banking screws are maintained by set screws F⁶ threaded into the machine frame and into engagement with the shanks of said screws F⁵.

During the shearing operation, it is essential that the mold holder be held against bending or outward displacement, and for this reason means are provided for guiding the mold holder at its outer or free end during its downward swinging movement past the trimming knife. These means include an arcuate shaped plate F⁷ (see Figs. 19 and 29), secured to a fixed portion of the machine and located so as to stand between the rearwardly offset end portion B⁵ of the mold holder and the end plate A⁸ of the mold. In other words, during the downward swinging movement of the mold holder, the rearwardly offset portion B⁵ thereof will engage against the rear face of the plate F⁷, when the mold holder arrives in the vicinity of the knife, and consequently the mold holder will be held against any knife reaction tending to displace or distort it outwardly during the shearing operation.

As the slug is ejected from the mold, it is forced, as usual, between a pair of trimming knives H and H¹ (see Figs. 11 and 19) which shave the side faces of the slug and bring it to the proper point size. The mounting and adjustment of these side trimming knives will be described later on, it merely being noted here that the knives are automatically set to correspond with the slot width of the mold in used. It may also be noted here that, during the ejection of the slug, the mold holder is held against forward displacement or distortion by the arcuate plate F⁷ which maintains its engagement with the holder when the latter is in its vertical ejecting position (Fig. 29).

Ejector construction and operation

When the mold A, after a slug casting operation, reaches its vertical ejecting position (Fig. 19), an ejector blade G is moved forwardly to push the slug out of the mold, between the knives H and H¹ (just referred to), and thence into a chute J through which slugs are led to a stacking tray J¹ at the front of the machine. In the present instance, the forward or active movement of the ejector blade is effected by pneumatic power under the control of a cam M⁶ on the main cam shaft M, although the cam itself effects the return of the ejector blade to its normal position of rest (Figs. 2, 18, 19 and 20).

As usual, the ejector blade consists of a series of blade sections G¹ arranged edge to edge and selectable for use (as will later be described) to vary the width of the blade in accordance with the length of the slot in the active mold. The active blade sections are connected to an operating slide G² arranged for fore-and-aft movement in fixed guides G⁵ of the machine frame. The slide G² is actuated by two toggle members G⁴ and G⁵ arranged at the left side of the slide and jointed as at G⁶. The toggle member G⁴ is rotatably mounted at its front end on a fixed pivot pin G⁷, whereas the toggle member G⁵ is pivotally connected at its rear end, as at G⁸, to a block secured to the slide G². When the parts are in the position shown in Fig. 2, the ejector slide G² is in its rearmost or inactive position, but when the foremost toggle member G⁴ is turned in a clockwise direction or to the position shown in Fig. 20, it will, through the other toggle member G⁵, pull the slide G² forwardly to project the ejector blade G through the mold slot and push

the slug therefrom. When the toggle member G⁴ is later rotated back to the position shown in Fig. 2, the ejector slide G² and, consequently, the blade G, will be restored to normal position.

The toggle member G⁴ is rotated in the manner just described by pneumatically operated mechanism mounted at the rear of the machine and comprising a cylinder G⁹ and a one-way acting piston G¹⁰. The piston G¹⁰ (Fig. 2) is connected to the toggle member G⁴ by linkage which includes, in part, a crank rotatably mounted on a fixed pivot pin G¹³ and formed with a rearwardly extending arm G¹¹ having a pin G¹² at its rear end engaging between two spaced collars G¹⁴ mounted on a piston rod G¹⁵ about midway of its length. The crank is also formed with a downwardly extending arm G¹⁶, terminating in a portion extending beneath the ejector guide assembly and provided at its free end with an anti-friction roller G¹⁷ arranged to engage the cam M⁶ previously referred to. A second arm G¹⁸, likewise rotatably mounted on the pivot pin G¹³ but secured to the crank arm G¹¹ by a pin G¹⁹ so as to rotate as a unit with said arm, is connected with the toggle member G⁴ by a long link G²⁰, whose connection G²¹ at its front end with the toggle member and whose connection G²² at its rear end with the arm G¹⁸ are both of a pivotal nature.

The whole arrangement is such that, as air is admitted into the lower end of the cylinder G⁹, the piston G¹⁰ will rise, causing the arms G¹¹ and G¹⁸ to swing as a unit in a clockwise direction and, through the link G²⁰, impart a similar movement to the toggle member G⁴ for the advance of the ejector slide. The movement of the arms G¹¹ and G¹⁸, however, is under the control of the cam M⁶, which is so formed that the movement of said arms will not occur until after the mold has arrived in the slug ejecting position. After the advance movement of the ejector slide has resulted in the ejection of the slug, the parts are restored to their normal position of rest by the cam M⁶ acting on the arm G¹⁶ through anti-friction roller G¹⁷. In this connection, it should be noted that the admission of air to the cylinder G⁹ is through an airline G²³ controlled from a valve (hereinafter identified) which is timed to admit air to the cylinder at the proper stage of the machine cycle. Furthermore, the construction of the valve is such that, during the return movement of the ejector slide to normal position, the cylinder below the piston is vented to the atmosphere so as not to retard the action.

It will be noted that the toggle arrangement herein employed acts in a manner which is the reverse of the usual case, i. e., it multiplies the pneumatic thrust at the beginning of the stroke, the mechanical advantage diminishing as the stroke advances. This is desirable since maximum resistance is afforded to the advance of the ejector blade at the moment when the slug breaks the hold of the mold. Pushing the slug between the trimming knives requires but moderate force which decreases as the slug advances. After trimming, very little force is required to push the slug into the galley.

The ejector mechanism includes certain safety devices, one of which acts to delay the admission of air to the cylinder in the event that the mold is delayed in reaching its slug ejecting position, and another of which acts to prevent operation of the ejector should the mold slot fail to register with the ejector blade and also to lock the mold in its slug ejecting position, once it has

arrived there, throughout the advance and return movements of the ejector blade. The first mentioned safety device has an additional function, namely, to cushion the mold holder as it arrives in its slug ejecting position.

The first safety device (Figs. 1 and 19) comprises a horizontal rod g slidably arranged in a housing g¹ and located so as to be engaged at its right end by the mold holder just prior to the arrival thereof in its vertical slug ejecting position. A centrally fulcrumed lever g², at its upper end, engages the rod g at the left and at its lower end engages the end of a piston g³ operating in a dash pot g⁴ which communicates with the atmosphere through a vent, the size of which is adjustable by a screw g¹³. The piston g³ is drilled out to house a compression spring g¹⁴ which reacts against the base of the dash pot, the arrangement being such that as soon as the mold holder leaves its normal position at the start of the casting cycle, the piston g³, under the action of the spring turns the lever g² in a clockwise direction from the position shown in Fig. 1, thereby moving the rod g to the right into a position to intercept the mold holder as it returns to the slug ejecting position. Then, when the mold holder upon its return strikes against the rod g, the final stage of such return movement will be against the cushioning effect of the spring g¹⁴ and the increasing pressure of the air trapped in the dash pot g⁴. Of course, the air pressure is soon neutralized by the vent so that the only force tending to unseat the mold holder is due to the spring. The mold holder thus will be brought to rest in its slug ejecting position against the fixed stop T, without shock or damage to the parts. The need for the buffer arrangement just described arises from the fact that occasionally there is a slight hesitation in the motion of the mold holder as the slug passes across the back knife in which case the movement of the holder to the ejecting position will be completed without the regulating influence of the cam M¹.

To perform its other function of delaying the operation of the ejector slide in the event that the mold holder is delayed in arriving in the slug ejecting position, the rod g is formed, about midway of its length, with a bevelled cam surface g⁵ arranged to engage the upper end of an angularly disposed push rod g⁶ which, at its lower end, is arranged to engage the stem of a valve g¹⁵ located in the air line or duct G²³ through which air is supplied to the cylinder G⁹ (Figs. 1, 2, and 19). The rod g⁶ is adjustable as to length and when the horizontal rod g is in its leftmost position, corresponding to the normal position of the mold holder, said rod g⁶ pushes on the valve stem to maintain the valve open. However, when the rod g moves to the right, which it does as soon as the mold holder starts its swinging movement up to casting position, the valve is permitted to close under spring action as the upper end of the push rod g⁶ rides down the bevelled cam surface g⁵ into the depression at the base thereof. Should it happen that the mold holder is delayed in its return to slug ejecting position the operation of the ejector is likewise delayed since the valve g¹⁵ will remain closed, so as to prevent the flow of air to the ejector operating cylinder G⁹, until the mold holder has pushed the horizontal rod g far enough to the left to cause the bevelled cam surface g⁵ thereon to move the rod g⁶ downwardly to open the valve g¹⁵. In other words, even

though in the ordinary operation of the machine, the stage of the casting cycle is reached at which air ordinarily would be admitted to the cylinder G^9 , the admission of air thereto will be delayed until the valve g^{15} is opened by the arrival of the mold holder in slug ejecting position. Rotation of the rod g about its longitudinal axis, which would destroy the alignment of the bevelled cam surface g^6 with the push rod g^8 , is prevented by a plate g^7 screwed to the housing at the left end thereof and which engages in a notch g^8 formed in the surface of the rod g . Furthermore, shoulders presented at the ends of the notch g^8 in cooperation with the plate g^7 serve to limit the movement of the rod g in both directions.

Since the possibility exists that the operation of the ejector mechanism might be delayed due to a delay in the return of the mold holder to slug ejecting position, provision is made for controlling the speed of operation of the ejector mechanism independently of the cam M^6 , since the latter would cease to control the operation of the ejector mechanism once the cam roller G^{17} departed from the edge of the cam which it would, did the possibility materialize. Under such conditions, the slug would be pushed out of the mold with great force upon the operation of the ejector mechanism were the additional speed control device not present.

The device just referred to (see Fig. 2) includes a fixed piston G^{24} mounted at the lower end of a vertical rod G^{25} secured at its top to a fixed part of the machine. The piston extends into a cylindrical recess drilled longitudinally into that portion of the ejector operating piston rod G^{15} which extends above the pin G^{12} connecting the piston rod with the lever G^{11} of the toggle operating linkage. The cylindrical recess is filled with oil so that it, in cooperation with the piston G^{24} , constitutes an oil dash pot which effectively controls the ejection speed under those conditions when the cam M^6 is unable to perform that function. Because of the force involved in slug ejection, the piston rod G^{15} is guided near its upper end in a bearing bracket G^{26} mounted on a fixed part of the machine.

The second safety feature alluded to, namely, the mechanism for locking the mold holder B against movement during the operation of the ejector blade G , is best illustrated in Figs. 1, 2, and 20. It includes a bar g^9 located at the left side of the ejector slide G near the lower end of the mold holder and guided in a block g^{16} for sliding movement in a fore-and-aft direction from its normal position (see Fig. 2), where it stands clear of the mold holder, to a forward or active position (see Fig. 20), where it engages in a notch b^2 provided for the purpose in the free end of the mold holder. The guide block g^{16} is arranged for limited adjustment in a lateral direction to insure that the bar g^9 will register with the notch b^2 when the mold holder banks against the fixed stop T .

Upon the arrival of the mold holder in slug ejecting position, the bar g^9 is projected forwardly into the notch b^2 and held therein during the advance and return movements of the ejector slide. However, after the return of the ejector slide to its normal position, the bar g^9 is moved rearwardly out of engagement with the notch b^2 to leave the mold holder free to swing upwardly to casting position in the next machine cycle of operation.

The fore-and-aft movement of the bar g^9 is effected through a lever g^{10} , whose lower end is pivotally connected to the rear end of the bar (Figs. 2 and 20). The lever g^{10} is fulcrummed near its center and, in the normal position of the parts (Fig. 2), engages at its upper end in a notch g^{11} formed in the rear edge of the front toggle member G^4 . However, when the toggle member G^4 is turned in a clockwise direction to advance the ejector slide, the lever g^{10} is cammed out of the notch g^{11} and into engagement with the lower edge portion g^{12} of the toggle member, which edge portion is concentric with the toggle member's fixed pivot point G^7 . The movement of the lever g^{10} out of the notch, and into engagement with the concentric edge portion g^{12} of the toggle member, is sufficient to move the bar g^9 to its foremost position and engage it in the notch b^2 of the mold holder. Here, it is pointed out that, because of the relative locations of the toggle members G^4 and G^5 , the active forward movement of the ejector slide G^2 will not take place until the toggle joint G^6 has moved upwardly as far beyond the dead center line as said toggle joint is below that line when the parts are in normal position. Consequently, while the initial movement of the toggle member G^4 will be idle so far as the actuation of the ejector slide is concerned, it will be effective to actuate locking bar g^9 and secure the mold holder temporarily in proper slug ejecting position.

As the toggle member G^4 continues its rotational movement to advance the ejector slide G^2 , the lever g^{10} will ride upon the concentric edge portion g^{12} of the toggle member and thus maintain the bar g^9 in its mold locking position. The bar g^9 will also remain in its locking position during the return movement of the toggle member G^4 and until after the ejector slide G^2 has been restored to its normal rearmost position. In the final stage of its return movement, the toggle member G^4 will present the notch g^{11} opposite the upper end of the lever g^{10} and, because of the shape of said notch and the shape of the adjacent end of the lever, the latter will be cammed positively into the notch. The rotational movement of the lever g^{10} resulting from such camming action will be sufficient fully to retract the bar g^9 from engagement with the notch b^2 in the mold holder.

In some cases, as for instance if a small chip became lodged between the mold holder and the stop T , a misalignment of the mold holder would occur which, however, might not be sufficient to prevent the opening of the valve g^{15} so that air would be admitted to the ejector operating cylinder G^9 . Under such circumstances, the forward movement of the bar g^9 would be prevented by the mold holder and this in turn would prevent the forward movement of the ejector slide since the toggle plate G^4 would be locked against rotation by the engagement in the notch g^{11} of the lever g^{10} , through which the bar g^9 is moved. The parts are so designed as to resist the pneumatic thrust with safety.

Before leaving the ejector mechanism, attention is called to the fact that should it become necessary to operate the ejector by hand, this can readily be accomplished by disconnecting the arm G^{18} from the crank member G^{11} merely by removing the pin G^{19} . To facilitate hand operation, the arm G^{18} is formed with an upwardly extending handle G^{27} which provides the necessary leverage.

Knife wiper

The machine is also equipped with a knife wiper which, during each machine cycle of operation, is dragged along the rear edges of the trimming knives H, H¹, prior to the slug ejecting operation, to free them of metal shavings that may have adhered thereto from the trimming of the previously ejected slug. The knife wiper mechanism includes a horizontal finger h (Fig. 1) extending laterally past the rear edges of the knives from the lower end of a vertical rod h¹ located at the left of the knives. The rod h¹ is guided for vertical movement in a pair of spaced brackets h² and h³ secured to fixed parts of the machine, the upper bracket h² being located near the top of the rod when the latter is in its normal lowermost position, while the lower bracket is arranged sufficiently high to permit the rod to be moved upwardly through a distance equal at least to the full length of the trimming knives H, H¹.

The vertical movement of the rod h¹ is effected through a long arm h⁴ (see Fig. 2) disposed in a fore-and-aft direction and pivotally mounted at its rear end on a fixed portion of the machine and bifurcated at its front end to engage a pin h⁵ projecting laterally from said vertical rod. The arm h⁴ in turn is operated from the rocker arm B¹⁷ through which the swinging movements of the mold holder B are effected (see Fig. 24). The operating mechanism includes a bell crank lever h⁶ fulcrummed at its center on the machine frame, and provided at one end with a pin h⁷ engaging between two spaced lugs h⁸ projecting laterally from the long fore-and-aft arm h⁴, and pivotally connected at its other end through a link h⁹ with an upwardly projecting post h¹⁰ formed at the top of the rocker arm B¹⁷.

According to this arrangement, when the parts move from the solid line to the dotted line position shown in Fig. 24 (which as will be recalled, corresponds to the upward swinging movement of the mold holder), the arm h⁴, and consequently the vertical rod h¹ actuated thereby, will be moved upwardly, causing the wiper blade h to be dragged along the edges of the slug trimming knives; whereas, when the parts are returned from the dotted line position to the solid line position shown in Fig. 24 (corresponding to the downward swinging movement of the mold holder), the wiper blade h¹ will again be dragged along the cutting edges of the knives in a downward direction. Since the operation of the knife wiper is under the control of the mold actuating mechanism, its timing is such as to complete the wiping action by the time the mold arrives in the slug ejecting position preparatory to the ejection of the slug.

Mold holder and ejector air valve mechanism

Insofar as the machine cycle of operation is concerned, there remains to be described the valve mechanism for controlling the flow of air to the cylinder and piston devices which effect the swinging movements of the mold holder and the to and fro movements of the ejector slide.

The valve mechanism (see Figs. 1, 36, 37 and 38) is located at the front of the machine near the base and includes, in part, a valve housing K having a body portion K¹ and a cap portion K² bolted together (Figs. 37 and 38) and mounted as a unit on a fixed portion of the machine. The cap portion K² presents a chamber K³ which is partitioned for a portion of its length so as to form two guideways K⁴ and K⁵. Air under pressure is supplied to the valve chamber K³ through

10 a passageway K⁶ formed in the body portion K¹ and which in turn is connected by an air duct K⁷ to a suitable source of air pressure. The chamber K³, in that portion constituting the valve guideway K⁴, is connected by a passageway K⁸ formed in the body portion K¹ with a duct K⁹ leading to the cylinder B²¹ associated with the mold holder actuating mechanism, whereas that portion of the chamber constituting the guideway K⁵ is connected through a similar passageway K¹⁰ with a duct K¹¹ leading to the cylinder G⁹ associated with the ejector slide operating mechanism. Within each guideway K⁴, K⁵, there is provided a valve slide K¹² spring-pressed into engagement with the adjacent body portion K¹ of the valve housing and adapted when in its uppermost position, as shown by the solid lines in Fig. 38, to connect the associated passageway K⁸ or K¹⁰ as the case may be, with the atmosphere through a recess K¹³ formed in the inner face of the valve slide. On the other hand, when the valve slides K¹² are in their lowermost positions, as shown by the dotted lines in said figure, communication with the atmosphere is cut off, and connection established between the high pressure chamber K³ and the respective cylinders B²¹ and G⁹ as the respective passageways K⁸ and K¹⁰ are uncovered.

20 The valve slides K¹² are moved to their different positions by rocker arms K¹⁴ fulcrummed at the center and connected at their opposite ends by ball and socket joints with the valve slides, on the one hand, and with a pair of vertical slide rods K¹⁵, on the other hand, there being one rod for each valve slide. The slide rods K¹⁵ are mounted in guideways formed in the body portion K¹ of the valve assembly, and are provided at their upper ends with antifriction rollers K¹⁶ held in engagement with a pair of overlying edge cams K¹⁷ and K¹⁸, by tension springs K¹⁹ connected by pins K²⁰ to the lower ends of the rods and pulling upwardly thereon from an overlying fixed portion of the valve housing. The cams K¹⁷ and K¹⁸ are made fast to a short fore-and-aft shaft K²¹, journaled in a fixed portion of the machine frame, and they are rotated once during each machine cycle of operation through a train of three gears K²², K²³ and K²⁴ (Fig. 1). The gear K²² is secured to the shaft K²¹, while the gear K²³, of the same diameter, is secured to the main cam shaft M. The third gear K²⁴, independently mounted, is an intermediate gear interconnecting the other two.

30 In Fig. 38 the parts are shown just after the commencement of the machine cycle. In the normal position of the parts, the antifriction roller K¹⁶ associated with the cam K¹⁷, engages the smaller concentric edge portion of the cam just in advance of the rise. Consequently, the slide rod K¹⁵ operating the valve slide K¹² will be in its upper position of adjustment, thereby locating the valve slide in a position wherein the cylinder B²¹ is charged with air pressure. The reason for this is to insure that the mold holder will be held firmly against its stop T so as to be in proper alignment for the interchange of molds as will be later described. The antifriction roller 35 K¹⁶ associated with the other cam K¹⁸, normally rests on the larger concentric portion of that cam so that the valve slide K¹² controlling the supply of air to the ejector operating cylinder G⁹, is in the position wherein air pressure is cut off from said ejector operating cylinder and the same vented to the atmosphere. Immediately after the start of the casting cycle, however, both antifriction rollers will ride on the larger concentric portions of their respective cams thereby positioning the valve slides so as to cut off the air

pressure from both cylinders and vent them to the atmosphere. Both cylinders B^{21} and G^9 remain vented to the atmosphere throughout most of the machine cycle, i. e., during the time required for swinging the mold holder from ejecting to casting position and for the slug casting operation. However, after the slug has been cast and the mold holder moved rearwardly ready for its return to the slug ejecting position, a low concentric portion of the cam K^{17} , which controls the valve slide K^{12} associated with the mold holder cylinder B^{21} , arrives opposite the associated antifriction roller K^{16} and permits the slide rod K^{15} on which it is mounted to move upwardly to the dotted line position shown in Fig. 38, thereby moving the connected valve slide downwardly to uncover the port K^8 leading to said cylinder B^{21} . As the air pressure builds up in the cylinder, it operates to restore the mold holder to the slug ejecting position, all in the manner hereinbefore described. Later on, and after the mold holder has arrived in its slug ejecting position, a low concentric portion of the other cam K^{18} arrives opposite its associated antifriction roller K^{16} , with the result that its respective slide rod K^{15} actuates the second valve slide K^{12} that admits air under pressure to the ejector slide cylinder G^9 in precisely the same way. Thereupon the ejector slide is operated to eject the slug as heretofore described.

The admission of air pressure to the mold holder cylinder B^{21} is maintained until immediately after the start of the next casting cycle, as previously stated; whereas, the air pressure to the ejector slide cylinder G^9 is cut off before the completion of the cycle since, it will be recalled, the cylinder G^9 must be vented to the atmosphere during the return movement of the ejector slide to its normal position of rest. Cut off for both cylinders occurs when the antifriction rollers K^{16} of the valve slides K^{15} travel from the smaller to the larger concentric portions of the cams.

Mold magazine and adjusting mechanism

As stated at the outset, while the mold holder B is adapted to carry a single mold only during the ordinary machine cycle of operation, the machine actually is equipped with a group of eight different molds, any one of which may be substituted for another in the mold holder at the will of the operator.

The molds A (see Figs. 1, 3 and 8), are stored in a magazine L located beneath the mold holder B in the normal or slug ejecting position of the latter. The magazine is open at the top and bottom and is formed with two side plates L^1 and L^2 spaced apart a distance equal to the overall width of the molds between the outer edges of the tongues A^5 and A^6 with which they are provided. A series of spacer plates L^3 is secured to each magazine wall on its inner face, said plates defining opposed grooves L^4 in which the tongues A^5 and A^6 of the molds slidably engage. The opposed spacer members at the front and rear ends of the magazine are interconnected by transverse straps L^5 properly to space the wall members L^2 , L^3 and lend rigidity to the structure. There are eight pairs of opposed grooves in all, each pair forming a pocket to accommodate a different mold.

The magazine L is supported for bodily movement in a fore-and-aft direction in an overlying fixed bracket L^6 presenting a pair of spaced rails L^7 which are engaged by two pairs of rollers L^8 spaced in a fore-and-aft direction and with

which the magazine is equipped at the top (Figs. 3, 14, 15). To permit the transfer of the individual molds to and from the magazine, the overlying bracket L^6 is formed with a transverse aperture L^9 located directly below the mold holder B when the latter is in its normal position (Fig. 3). The molds A are supported in the magazine by underlying springs L^5 which engage beneath the mold end plate members A^8 (Fig. 15). As will now be clear, by moving the magazine L forwardly or backwardly, any selected mold may be brought into alignment with the mold holder B for transfer thereto and later transfer therefrom, the mold during such transfer operations passing endwise through the aperture L^9 in the mold magazine supporting bracket L^6 .

Such fore-and-aft adjustment of the mold magazine is controlled by the operator from the front of the machine. For this purpose, there is provided a control handle P mounted at the right end of a short transverse shaft P^1 journaled in a fixed part of the machine (Fig. 1). A downwardly extending arm P^2 , pinned to the transverse shaft P^1 at the left, is formed at its lower end with a gear segment P^3 meshing with a pinion P^4 mounted near the right end of a second transverse shaft P^5 journaled in a fixed part of the machine. At the left end of the transverse shaft P^5 (Fig. 15), there is mounted a sleeve P^6 constrained to rotate with the shaft by a pin and slot connection P^7 but which is permitted a limited longitudinal movement with respect to the shaft, for a purpose hereinafter described. A pinion P^8 , formed integrally with the sleeve, meshes with a fore-and-aft rack bar l fastened to the mold magazine L at the lower right hand edge thereof. As a result of this arrangement, when the handle P is moved upwardly (Fig. 1), the transverse shaft P^5 , through its gear and pinion connections with the handle P , will rotate in a counterclockwise direction (looking at the parts from the right) and, since the sleeve P^6 partakes of the same rotary motion as the shaft, the magazine L will be adjusted in a forward direction. Conversely, when the handle P is moved downwardly, the transverse shaft P^5 will be rotated in the opposite direction to adjust the mold magazine rearwardly.

Since the movements of the control handle P and the mold magazine L are synchronized, it follows that the handle will have a given position for each different mold transfer position of the mold magazine. The different positions of the handle P are determined by a pin P^9 arranged to engage in one or another of a series of apertures P^{10} formed in a sector plate P^{11} arranged adjacent the handle P (Figs. 4 and 5). The pin P^9 is arranged for transverse sliding movement in the handle P and is pivotally connected at one end to an arm P^{12} extending rearwardly from a hand grip P^{13} pivotally mounted on and forming part of the handle P . A spring P^{14} , reacting between the handle P and an abutment P^{15} on the handle grip P^{13} , urges the latter to the solid line position shown in Fig. 5, wherein the pin P^9 seats in one or another of the apertures P^{10} . However, during the selection of a mold, the hand grip P^{13} is turned to the dotted line position shown in Fig. 5, thereby withdrawing the pin P^9 from the aperture and leaving the handle free for movement in the selection of any particular mold. Since each aperture P^{10} corresponds to a different mold in the magazine, the presence of the pin P^9 therein will insure that the corresponding mold is in proper transfer position.

The sector plate P^{11} is formed with laterally extending flanges at the top, bottom and front, the front flange presenting a series of windows P^{16} in different positions corresponding to the different adjusted positions of the handle P (Figs. 6 and 7). A backing plate P^{17} for the front flange presents a series of pockets P^{18} registering with the windows and which are adapted to receive cards or plates symbolic of the mold which will be located in the transfer position when the handle P is correspondingly adjusted. The symbols on the plates indicate the point size and em length of the corresponding molds. For the sake of appearance, there is provided a plate P^{19} joining the top and bottom flanges of the sector plate except for a short distance near the front flange, where a space is left through which the hand grip P^{13} extends. Otherwise the handle P is completely enclosed. The closing plate P^{19} also serves to limit the movement of the hand grip P^{13} when it is turned to withdraw the pin P^{19} from the aperture wherein it is engaged (Fig. 5).

The mold magazine L is mounted so that it can be removed from the machine and loaded with any desired combination or series of molds. As shown in Figs. 14, 15 and 17, when the mold magazine has been adjusted to its extreme forward position by the upward movement of the handle P as just described, a segmental recess l^1 in a plate P^2 , which ordinarily overlaps the mold moving pinion P^8 , is brought into registry with the pinion so that the latter may be drawn laterally out of engagement with the rack l . When the pinion P^8 is disengaged from the rack l , the mold magazine is free to be pulled forward and removed from the machine. The lateral movement of the pinion P^8 is permitted by the before-mentioned pin and slot connection P^7 by which the sleeve P^6 , formed integrally with the pinion, is splined to the shaft P^5 . Normally, the sleeve and consequently the pinion are held against movement along the shaft P^5 by a compression spring p encircling the shaft and reacting between a fixed portion of the machine 45 and an annular recess in the sleeve. However, when the removal of the mold magazine is desired, the sleeve is moved against the action of the spring p to the dotted line position shown in Fig. 15, a knurled grip p^1 being formed on the 50 sleeve to facilitate its operation.

Upon the return of the mold magazine to the machine, it is essential that it be located so that the adjustment of the mold selecting handle P to its different positions will result in bringing the corresponding mold into the transfer position. In other words, since the segmental recess l^1 in the bar P^2 permits reengagement of the adjusting pinion P^8 with the rack l only when the mold magazine is adjusted to locate the rear-most mold in the transfer position, it is essential that the pinion P^8 be adjusted during its reengagement to locate the mold selecting handle P in the corresponding position. To this end, there is provided a plate P^2 secured to the face 65 of the pinion P^8 at the side thereof opposite that which is overlapped by the plate P^2 on the mold magazine. The plate is circular and has a diameter equal to the overall diameter of the pinion except in one position, where a segment 70 of the plate is cut away to present a straight edge p^3 at the base of the pinion teeth (Fig. 17). Hence, the pinion P^8 can be slid laterally into engagement with the rack l only when this straight edge portion is parallel with the rack. 75

Since the parts are constructed so that the straight edge portion p^3 will be parallel with the rack only when the mold locating handle P is in the position corresponding to that which locates the rearmost mold in the transfer position, the proper cooperative relation between the handle P and the mold magazine will be insured under all conditions.

Of course, when any change is made in the disposition of the molds in the magazine, a corresponding change will be made in the indicia plates in the sector element adjacent the mold selecting handle P . The pockets P^{18} containing these plates are open at one edge to facilitate the 15 substitution (Figs. 5, 6 and 7).

Mold transfer mechanism

The molds A are transferred from the magazine L to the mold holder B and vice versa by a transfer slide L^{10} arranged for vertical movement 20 in a guide bracket L^{11} , which latter is secured to the machine frame, beneath the mold magazine in such position that the transfer slide is in vertical alignment with the mold holder in its normal position of rest (Figs. 1 and 3). When the transfer slide L^{10} is in its lowermost position (Fig. 15), as determined by the engagement of a forwardly projecting pin L^{12} thereon with the upper edge of the guiding bracket L^{11} , it will be in position to engage the bottom end of the mold which, at the time, is in registry with the mold holder. The transfer slide is formed with a laterally projecting nose portion L^{13} arranged to overlie a similar nose portion A^{10} projecting laterally in the opposite direction from a downwardly extending portion of the mold end plate A^8 . In other words, the arrangement is such that the transfer slide, in its lowermost position, cannot interfere with the fore-and-aft movement of the mold magazine during the selection of a mold for use. Its construction is such, however, that when raised it will push the mold which has been adjusted into registry with it up into the mold holder, and when lowered, it will withdraw the mold out of the mold holder back into its proper position or pocket in the magazine. Furthermore, when the transfer slide L^{10} has transferred the selected mold to the mold holder, it remains in its raised position so long as that mold is continued in use (see Fig. 2) and thus remains in readiness to remove the mold from the holder when desired. The transfer slide performs the additional function of holding the mold magazine against inadvertent adjustment when a mold occupies the mold holder, the slide for this purpose being arranged (see Fig. 15) to extend at the left into the groove L^4 of the vacant pocket.

Throughout the normal operation of the machine, the transfer slide L^{10} is held in its raised position by a horizontal rotatable bar L^{14} journaled in a fixed portion of the machine and located beneath a vertical rib l^4 projecting rearwardly from the transfer slide (see Figs. 8 and 9). The location of the bar L^{14} is such as to maintain a slight clearance between the interengaging nose portions L^{13} and A^{10} on the transfer slide and mold, respectively, and also between the adjacent edges of the slide and mold, so as not to interfere with the swinging movements of the mold holder in normal machine operation. The bar L^{14} at its left end is reduced to a half-round section and, during the substitution of one mold for another, is rotated from the position shown in Fig. 9 to the position shown in Fig. 10 so as not to interfere with the movements of the

transfer slide. The means for adjusting the bar to its different positions will be described later on.

The raising and lowering of the transfer slide L^{10} for mold substitution is accomplished by pneumatic power. To this end, the transfer slide is operated by a fore-and-aft arm L^{15} pivotally mounted at its rear end in a fixed portion of the machine (see Figs. 3 and 4) and pivotally connected at its front end to the transfer slide by a link L^{16} . About midway of its length the arm L^{15} is pivotally connected by means of a vertical link L^{17} to the front end of another arm L^{18} located somewhat higher up and which is likewise pivotally mounted near its rear end on a fixed pivot. Between its end connections, the arm L^{18} engages in a recess presented near the upper end of a vertical piston rod L^{19} operating in a cylinder L^{20} having connections for supplying air under pressure thereto both above and below the piston. When air is introduced at the bottom of the cylinder below the piston, the transfer slide operating linkage just referred to is moved from the position shown in Fig. 3 to the position shown in Fig. 4, with the result that the mold in register with the transfer slide is pushed upwardly into the mold holder. Conversely, when air is introduced into the cylinder above the piston, the linkage is moved from the position shown in Fig. 4 back to the position shown in Fig. 3, with the result that the mold which was located in the mold holder is drawn downwardly into its proper pocket in the magazine.

Air is supplied to the upper and lower ends of the cylinder L^{20} through a pair of air ducts not shown but which communicate with a valve L^{21} located near the front of the machine (Figs. 1, 12 and 35). The valve (Fig. 35) includes a housing L^{22} mounted on a fixed bracket and formed with a chamber L^{23} , a valve slide L^{24} located in the chamber, and a rocker arm L^{25} , these parts being similar to those used for controlling the flow of air to the cylinders of the mold holder and ejector actuating mechanisms, except that here a single valve slide and rocker arm are used. When the valve slide L^{24} is in the position shown by the full lines in Fig. 35, air under pressure from a suitable source enters the valve chamber L^{23} through a connection L^{26} , passing then through a connection L^{27} at the right of the housing to the top of the cylinder L^{20} . At the same time, the lower end of the cylinder is vented to atmosphere through a connection L^{28} at the left of the housing and through a recess (not shown) in the valve slide. On the other hand, when the rocker arm L^{25} is turned to the dotted line position shown in Fig. 35, the connections are reversed, i. e., air under pressure is supplied to the lower end of the cylinder through the connection L^{28} , whereas the top of the cylinder is vented to atmosphere through the connection L^{27} . The devices for actuating the valve in the substitution of one mold for another will later be described.

Before a mold located in the mold holder can be removed therefrom and another substituted in its place, the mold locating and locking devices B^8 and B^{14} (Figs. 26 and 27) must be released in order to free the mold for movement by the transfer slide L^{10} . The connections for this purpose include in part a rod N (Fig. 27) extending in a fore-and-aft direction through the hollow rock shaft B^7 and guided near its front end in a bracket N^2 secured to the mold holder and which extends rearwardly therefrom. The rod is slotted near its front end to accommodate the latch

member B^8 which extends through the slot and is located between two pins n and n^1 extending transversely of the slot. A tension spring N^1 connected at its front end to the latch and at its rear end to the bracket N^2 , serves to hold the latch in its active position and since the latch engages the rearmost pin n^1 , the spring serves to hold the rod N in a normal retracted position. At its rear end (Fig. 25), the rod N projects beyond an end closing plate B^{31} with which the rock shaft is provided and in which the rod is supported for endwise movement. Here the rod is formed with a vertical notch which, when the rock shaft is in its normal position, embraces a pin N^3 projecting laterally from an upwardly extending arm of a bell crank lever N^4 . This bell crank lever N^4 (Fig. 4) is mounted on a fixed transverse pivot N^5 and is formed also with a rearwardly extending arm which at its rear end is pivotally connected at the top of a vertical link N^6 , the link in turn being pivotally connected at its lower end to a laterally extending arm N^7 fixed on a fore-and-aft rock shaft N^8 . When the fore-and-aft rock shaft N^8 is turned in a clockwise direction, looking at the parts from the front, or from the position shown in Fig. 4 to the position shown in Fig. 3, the rod N , through the linkage just described, is pushed forwardly thereby causing the transverse pin n to rock latch B^8 from its active or mold locking position to its inactive or mold releasing position. Later, when the substitute mold has been located in the mold holder by the upward movement of the transfer slide, the fore-and-aft rod N is moved rearwardly to its normal position through its link connections with the fore-and-aft rock shaft N^8 by a reverse or anti-clockwise movement of the latter. Such rearward movement of the fore-and-aft rod N causes the transverse pin n at the front of the latch B^8 to restore the same to its active position thereby causing the lower nose portion B^{11} thereof to engage in the locating notch A^9 of the substitute mold, it being understood that all of the molds are provided with such a notch. Likewise extending through the hollow rock shaft B^7 , is a second fore-and-aft rod N^9 slidably supported, at its rear end, in the rock shaft end plate B^{31} and extending, at its front end, through the head of the mold holder B (Figs. 5, 26, and 27). The rod N^9 operates the mold locking cams B^{14} , being formed at its front end with rack teeth N^{10} arranged to mesh with gear teeth N^{11} formed at the left end of a pinion N^{12} rotatably mounted in a transverse cylindrical recess formed in the head of the mold holder. The pinion N^{12} is held against endwise movement by a locating screw N^{13} threaded into the mold holder at the top and which has a reduced plain lower end engaging in an annular groove formed in the cylindrical surface of the pinion. At its right end, the pinion N^{12} is formed with another set of gear teeth N^{14} meshing with rack teeth N^{15} provided at the upper end of a bar N^{16} arranged for vertical movement in a recess N^{17} formed in the right edge of the mold holder B , the bar being held in proper position within the recess by a retaining plate B^{32} fastened to the mold holder by offset straps B^{33} screwed thereto at the front. Near its lower end, the bar N^{16} is provided with another set of rack teeth N^{18} meshing with a pinion N^{19} secured to the hub portion of the locking cams B^{14} . When the parts are in their normal positions, any play that might be present in the connections is taken up by a compression spring N^{20} housed in an enlarged portion of the recess N^{17} and which re-

acts between the upper end of said recess and a pin N^{21} extending inwardly from said bar. In other words, the spring N^{20} reacts downwardly on the bar N^{16} which, through the rack N^{18} and pinion N^{19} , urges the locking cams in a clockwise direction to clamp the mold in the mold holder.

The fore-and-aft rod N^9 within the rock shaft B^7 is coupled for movement to the other fore-and-aft rod N , i. e., the one associated with the latch B^8 , the coupling including a finger N^{22} formed integrally with a sleeve pinned to the rod N and extending through a slot in the rod N^9 . Hence, when the rod N is moved forwardly in the manner previously described to render the latch B^8 inactive, the second rod N^9 partakes of the same movement and, through its rack and pinion connection with the vertical bar N^{16} , moves the latter upwardly against the action of the compression spring N^{20} , thereby turning the locking cams B^{14} in a counterclockwise direction to release the mold. After the latch B^8 and the cams B^{14} have thus been rendered inactive, the mold A is free for withdrawal from the mold holder B by the downward movement of the transfer slide L^{10} . When the rod N is later moved rearwardly to engage the latch B^8 with the substitute mold, the cams B^{14} are turned to active or mold clamping position by the spring N^{20} acting upon the rod N^{16} . In this connection, it should be stated that the slot in the rod N^9 into which the coupling finger N^{22} extends, is large enough to accommodate any variation in movement of the rod N^9 occasioned by variations in the thickness of the mold liners of the different molds, while still permitting the necessary movement of the rod N properly to operate the latch B^8 .

From what has been said, it is apparent that the substitution of one mold for another involves three operations preparatory to the selection of the mold and then three operations which are the reverse thereof after the mold has been selected. The three preparatory operations include, first, the release of the mold in the mold holder by rendering inactive the latch B^8 and the cams B^{14} ; second, the release of the transfer slide L^{10} by rendering inactive the bar L^{14} that normally holds the transfer slide in its uppermost position, and third, the movement of the transfer slide L^{10} downwardly to transfer the mold then in use from the mold holder into the mold magazine. These operations are controlled from a single handle O located at the front of the machine and within easy reach of the operator (Figs. 1 and 12). As shown, the handle O is mounted in a bracket O^1 fixed to the machine frame and formed with two spaced side members O^2 , a rear spacing and strengthening strap O^3 , and a top member O^4 provided with a U-shaped slot O^5 through which the handle O extends. At its lower end, the handle is bifurcated to straddle a transverse rock shaft O^6 to which it is pinned and which shaft is supported for endwise or axial movement, at the right in the bracket O^1 and at the left in a slide bearing O^7 fixed to the machine frame. Approximately midway between its ends, the handle O has a swivel mounting constituted by an enlarged circular portion O^8 which engages between two opposed buttresses O^9 extending inwardly from the side members O^2 of the bracket.

At the left end of the rock shaft O^6 , i. e., just beyond the slide bearing O^7 , there is mounted a shoe O^{10} (Figs. 1, 12 and 35) pinned to the shaft and extending downwardly for a short distance. At its lower end, the shoe is formed with a portion extending to the right, which

portion is provided in its lower face with a longitudinal groove O^{11} wherein the aforementioned rocker arm L^{23} engages at its upper end. The rocker arm L^{25} , it will be recalled, is the one operating the valve which controls the transfer slide actuating mechanism.

The three preparatory operations above referred to are accomplished simply by moving the handle O uninterruptedly from one end of the U-shaped slot to the other. The initial or normal position of the handle is designated 1 (Fig. 1), and during its movement, it will occupy sequentially three other positions, designated 2, 3 and 4, respectively. When the control handle is in its normal position, i. e., position 1, the shoe O^{10} occupies the solid line position shown in Fig. 35 in which position the adjustment of the valve slide L^{24} is such as to admit air to the top of the cylinder L^{20} . In other words, in the normal position of the parts, air pressure in cylinder L^{20} tends to draw the transfer slide L^{10} downwardly, but such action is prevented by the locking bar L^{14} located beneath the transfer slide as previously noted. However, when the control handle O is moved to position 2, it rocks the shaft O^6 clockwise, looking at the parts from the right, thereby turning the shoe O^{10} to the dotted line position shown in Fig. 35, with the result that the valve slide L^{24} is adjusted to admit air to the cylinder L^{20} below the piston. Thereupon, the transfer slide L^{10} is moved up slightly, as permitted by the clearance between its upper edge and the lower edge of the mold end plate A^8 , away from the transfer slide locking bar L^{14} and thereby freeing the latter for rotation.

When the handle O is moved from position 2 to position 3 (Fig. 1), the shaft O^6 connected at the lower end thereof is shifted edgewise to the right, the enlarged circular portion O^8 in cooperation with one of the buttresses O^9 acting as a fulcrum about which the handle pivots during such movement. The shoe O^{10} connected at the left end of the shaft of course moves along with it, the movement being permitted by the groove O^{11} which is long enough to allow the shoe to move the necessary distance laterally with respect to the valve rocker arm L^{25} without disturbing its setting. This endwise movement of the shaft O^6 and shoe O^{10} accomplishes two operations: first, the rotation of the transfer slide lock L^{14} to its inactive position, thereby releasing the transfer slide for downward movement; and, second, the clockwise rotation of the fore-and-aft rock shaft N^8 which renders inactive the latch B^8 and the cams B^{14} that locate and clamp the mold in the mold holder. The two operations just referred to are effected through an arm O^{11} pinned at its center to the fore-and-aft rock shaft N^8 and swivelled at its upper end to the shoe O^{10} , as shown in Fig. 1. At its lower end, the arm O^{11} is provided with a pin O^{12} engaging in a cam slot O^{13} formed in a sleeve O^{14} fixed at the end of the transfer slide locking bar L^{14} (Figs. 8, 9 and 10). When the shoe O^{10} moves to the right, the arm O^{11} is rocked in a clockwise direction (looking at the parts from the front of the machine), thereby moving the fore-and-aft rock shaft N^8 in the same direction, and also moving the pin O^{12} to the left. The shape of the cam slot O^{13} is such that the movement of the pin O^{12} causes the locking bar L^{14} to turn through an angle of 45° from its locking position shown in Fig. 9 to its unlocking position shown in Fig. 10.

When the handle O moves from position 3

to position 4 (Fig. 1), the rock shaft O^6 and the shoe O^{10} move back to the solid line position shown in Fig. 35, wherein, as will be recalled, the valve slide L^{24} is adjusted to admit air to the top of the cylinder L^{20} above the piston and to vent the lower end of the cylinder to the atmosphere. Since the transfer slide and mold connected thereto are now free to move, the resultant movement of the piston rod L^{19} will actuate the transfer slide downwardly, thereby drawing the mold out of the mold holder and into its proper pocket in the mold magazine.

While the handle O is in position 4, the operator adjusts the mold magazine L forwardly or rearwardly (in the manner previously described) to bring the newly selected mold into a position in registry with the mold holder B at the top and the transfer slide L^{10} at the bottom so that it can be moved upwardly by the latter into the mold holder.

After such adjustment of the mold magazine, the operator merely returns the control handle O to its original position (Fig. 1), and during the course of its return movement, it will pass uninterruptedly from position 4 to position 3, then to position 2, and finally to position 1. The first movement of the handle from position 4 to position 3 will, through the rock shaft O^6 and the shoe O^{10} , adjust the valve slide L^{24} to the dotted line position shown in Fig. 35, admitting air to the bottom of the cylinder L^{20} and causing the piston rod L^{19} to actuate the transfer slide L^{10} upwardly to lift the newly selected mold from the magazine into the mold holder (Fig. 4). The second movement of the handle O from position 3 to position 2 shifts the rock shaft O^6 and the shoe O^{10} endwise to the left, rocking the arm O^{11} in a counterclockwise direction back to its original position. This rocking movement of the arm O^{11} , through its pin and cam slot connection with the transfer slide locking bar L^{14} , will rotate the latter from its unlocking position shown in Fig. 10 back to its locking position shown in Fig. 9. At the same time, the arm O^{11} turns the fore-and-aft rock shaft N^8 in a counterclockwise direction back to its original position, thereby rendering active the latch B^8 and the cams B^{14} to lock the new mold in proper position in the mold holder, all as previously described. Should the transfer slide locking bar L^{14} be prevented by the transfer slide from returning to its normal active position, indicating that something has interfered with the movement of the substitute mold into the holder, the operator will be apprised of that fact since the movement of the control handle O from position 3 to position 2 will be arrested. And even though the mold has moved up far enough to permit operation of the locking bar L^{14} but still fails to reach its uppermost position, due to say, a chip preventing the mold from making proper contact with its overlying stop, that knowledge likewise will be brought to the attention of the operator. In this instance, the latch B^8 will fail to enter the notch provided for it in the mold end plate, and since the connections between the latch and the handle O are all positive, the handle O similarly will be arrested in its movement from position 3 to position 2.

When the handle O moves from position 2 to position 1 (Fig. 1), air is cut off from the lower end of the cylinder L^{20} and is admitted instead to the top end thereof. This results in moving the transfer slide L^{10} downwardly a slight distance until arrested by the underlying lock bar

L^{14} , the location of which (as before stated) is such that it will hold the transfer slide in a position providing sufficient clearance between the upper edge of the transfer slide and the adjacent edge of the mold end plate A^8 so as not to interfere with the swinging of the mold in the operation of the machine, and also in a position wherein there will be no binding action between the overlapping nose portions L^{13} and A^{10} on the slide and the mold end plate, respectively.

At this point, it might be stated that the connection between the fore-and-aft rod N through which the mold locking devices are operated, and its actuating lever N^4 is such as not to interfere with the normal operation of the machine. As the rock shaft B^7 swings during normal machine operation, the recess near the rear end of the rod N rides away from the pin N^3 but automatically reengages the pin N^3 when the rock shaft returns to its normal or slug ejecting position. Throughout the rock shaft movement, the normal longitudinal position of the rod N is maintained by the tension spring N^1 reacting through the latch B^8 .

Automatic ejector blade adjustment

When one mold is substituted for another in the mold holder, the new mold may differ from its predecessor as regards the length of its mold slot, and consequently, the ejector blade width will require adjustment to correspond. According to the present improvements, this adjustment is effected automatically during the interchange of the molds.

The ejector blade G (Figs. 19 and 20) is of standard construction, consisting of a series of blade sections G^1 arranged edge to edge in superposed relation and guided at the right by a fixed fore-and-aft side plate R . The blade sections are also guided at the front by a vertical plate R^1 extending laterally from a fixed portion of the machine so as to define, together with the guide plate R , a vertical slot through which the ejector blade moves in performing its slug ejecting function. The blade sections G^1 are operated by the ejector slide G^2 through a series of individual horizontal slides R^2 guided, at the front in notches formed in a vertical plate R^3 secured to a fixed portion of the machine and, at the rear, in individual grooves R^4 formed in the ejector slide itself (Figs. 18 and 19). A connecting bar R^5 , arranged for vertical adjustment, is mounted in a groove R^6 cut in the face of the ejector slide and engages at the rear of the individual slides R^2 . In operation, the selected blade sections are pushed forwardly through the intermediate slides when the ejector slide G^2 is actuated to eject a slug and subsequently, after the ejection of the slug, they are drawn rearwardly by a vertical plate R^7 secured at the front of the ejector slide and arranged to engage shoulders R^8 presented by the respective slides R^2 .

In its different vertical positions of adjustment, the bar R^5 will engage a different number of blade section actuating slides R^2 as may be required by the slot length of the mold in use. The bar R^5 moves in a fore-and-aft direction with the ejector slide, and those individual slides R^2 which, under a given adjustment, are not engaged by the bar will remain stationary during such movement. The connecting bar R^5 , at its lower end, is slidably connected to a fore-and-aft rod R^9 and slides idly thereon during the operation of the ejector (Fig. 20). At its rear end, the rod

R^9 is connected to a slide R^{10} mounted for vertical adjustment in guideways R^{11} formed in a bracket fixed to the machine frame, the arrangement being such that as the slide R^{10} is adjusted to different levels a corresponding adjustment of the connecting bar R^5 itself will take place, all as well understood in the art.

Coming now to the present improvements, the vertical adjustment of the slide R^{10} is determined by the position of a fore-and-aft lever R^{12} pivotally mounted at its center on a fixed portion of the machine and connected at its rear end with the slide R^{10} by a laterally extending pin R^{13} engaging in a recess formed in the slide (Figs. 2 and 8). At its front end, the lever R^{12} is formed with another laterally extending pin R^{14} arranged to engage one or another of a series of stops R^{15} carried by the mold magazine L at the left side thereof. There is one such stop R^{15} for each mold in the mold magazine and for any given adjustment of the mold magazine, the stop corresponding to the mold in transfer position will be located in engaging relation to the pin R^{14} of the lever R^{12} .

The stops R^{15} are arranged for vertical adjustment along the left side wall of the magazine L , and for this purpose they are formed with laterally extending tongues R^{16} arranged to slide in grooves R^{17} presented by said wall (Figs. 15 and 16). Each stop R^{15} is maintained in its adjusted position by a spring-pressed detent R pivotally mounted on the stop and formed with a lip R^{19} which engages in one or another of a series of vertically spaced notches R^{20} likewise formed in the side wall of the mold magazine at the base of each groove R^{17} . As shown in Fig. 16, the notches R^{20} are located so as to correspond to different length molds. Thus, if the length of the casting slot in a given mold in the magazine is four ems in length, the stop R^{15} corresponding to that mold will be adjusted so that its detent R^{18} engages the topmost notch labeled 4, or if the mold length is thirty ems, the detent will be adjusted to engage the lowermost notch labeled 30. For any intermediate length of mold slot, the stop will be correspondingly adjusted with the aid of the other labels.

From what has been said, it will be apparent that the adjustment of the lever R^{12} will depend upon the location of the active stop R^{15} , and since the number of ejector blade sections depends in turn upon the adjustment of that lever, proper setting of the stops will automatically give an ejector blade width corresponding to the length of the slot in the active mold. The adjusted position of the lever R^{12} is maintained by a tension spring R^{21} connected thereto at its front end and anchored to a fixed part of the machine (Fig. 2).

The operation of the lever R^{12} is as follows (Figs. 2, 3 and 8): When air is admitted to the upper end of the cylinder L^{20} to transfer the then active mold A back into the mold magazine L , an arm r , integral with but offset to the right of the lever L^{18} of the transfer slide actuating linkage, is rocked downwardly as said lever is moved in a clockwise direction under the action of the downwardly moving piston rod L^{19} . At its front end, the arm r engages a lug r^1 offset from the lever R^{12} about midway between its fulcrum point and its rear end where it is connected to the slide R^{10} . Consequently, the lever R^{12} will be swung from its previous position of adjustment as shown in Fig. 2 to the neutral position shown in Fig. 3, with the result that the slide R^{10}

will be moved to its lowermost position of adjustment (representing a zero or minimum ejector setting); whereas the pin R^{14} at the front end of the lever will be located sufficiently high to override all of the stops R^{15} on the magazine L , i. e., above the level of a stop adjusted to the topmost notch, which is the adjustment for a mold slot four ems in length.

Thereupon, as will be recalled, the operator 10 adjusts the mold magazine L in a fore-and-aft direction to bring the desired mold into the transfer position. With such adjustment of the mold magazine, the stop R^{15} thereon corresponding to the newly selected mold will be brought 15 into position for engagement with the pin R^{14} of the adjusting lever R^{12} , it being understood, of course, that all of the stops R^{15} are properly adjusted when the magazine is loaded prior to its insertion in the machine.

20 Now, as air is introduced into the lower end of the cylinder L^{20} to transfer the selected mold upwardly into the mold holder B , the arm r is rocked in a counterclockwise direction along with the lever L^{18} . That movement of the arm r allows the lever R^{12} to swing in a clockwise direction under the influence of the spring R^{21} until it is arrested by the engagement of the pin R^{14} with the stop R^{15} corresponding to the newly selected mold. The lever R^{12} remains in that 25 position of adjustment, although the arm r continues upwardly to its normal position. During the adjustment of the lever R^{12} , the slide R^{10} connected at the rear end thereof moves upwardly to the position determined by the new setting, 30 the slide in turn raising the vertical bar R^5 to connect the proper number of ejector blade sections G^1 for operation by the ejector slide G^2 in accordance with the slot length on the newly selected mold (now transferred to the mold holder).

Automatic knife adjustment

When one mold is substituted for another in the mold holder, the new mold may likewise vary from its predecessor as regards the width of the mold slot and such variation requires an adjustment in the spacing of the slug trimming knives. In the improved machine, this adjustment is also effected automatically during the substitution of one mold for another.

As shown in Fig. 19 the lefthand knife H is stationary, whereas the righthand knife H^1 is adjustable toward and from the same. The lefthand knife H (Figs. 11 and 19) is mounted in a holder S and the righthand knife in a separate holder S^1 , being held therein by screws S^2 passing through the knives and threaded into the holders. Proper adjustment of the knives with respect to their holders is obtained by adjustable set screws S^3 and maintained by screws S^3^1 .

The lefthand knife holder S is stationary, being secured to a fixed part of the machine. The righthand knife holder S^1 , on the other hand, is adjustable, being made in the form of a rectangular frame encompassing both knives and provided at the left with a horizontal extension S^4 slidably arranged in a fixed portion of the machine frame. The slide extension S^4 is recessed to receive a spring S^5 reacting between a pin S^6 , backed up by a fixed abutment S^7 at the left, and a portion of the slide at one end of the recess, the arrangement being such that the knife frame is urged constantly toward the right.

The righthand knife frame S^1 is also formed 75 with a lug S^8 projecting therefrom at the right

and its adjusted position is determined by the engagement of said lug with one or another of a series of banking pins S^9 threaded into an inclined face of a vertically adjustable slide S^{10} which is tongued and grooved to a fixed portion of the machine frame (Figs. 11 and 19). By adjusting the slide S^{10} upwardly or downwardly to render the proper banking pin S^9 active, the knives will be spaced to correspond with a given mold slot width.

The mechanism for adjusting the slide S^{10} includes the fore-and-aft rock shaft N^8 before referred to and which, as will be recalled, controls the operation of the mold locating and locking devices. At the front end of the shaft N^8 , there is fixed a crank arm S^{11} which at its free end is pivotally connected to an upwardly extending rod S^{12} guided at the top for vertical movement in a slotted plate S^{13} fixed to the mold magazine supporting bracket (Figs. 11 and 12). At its upper end, the rod S^{12} engages beneath an overlying arm S^{14} of a bell crank lever S^{15} pivotally mounted on that portion of the fixed frame which supports the lefthand knife (Figs. 11 and 12). The bell crank lever is formed with another arm S^{16} extending upwardly from the pivot point, and which is bifurcated at its upper end where it engages a pin S^{17} projecting rearwardly from the righthand knife supporting frame S^1 .

With this arrangement, when the fore-and-aft rock shaft N^8 is turned in a clockwise direction by the endwise movement of the transverse rod O^6 under the control of the handle O as the latter is shifted from position 2 to position 3 during the interchange of molds, (all as previously described), the vertical rod S^{12} is moved upwardly, thereby rotating the bell crank lever S^{15} in a direction to shift the righthand knife frame S^1 to the left against the action of the compression spring S^5 , until the two knives have a zero or minimum spacing. That setting of the knives is maintained until the rock shaft N^8 is restored to its normal position after the selection of the substitute mold.

While the minimum spacing of the knives is maintained, the abutment pin block S^{10} is adjusted to render that pin S^9 operative which will space the knives in accordance with the slot width of the selected mold. Parenthetically, the mechanism for this purpose is very similar to that for adjusting the ejector blade width. The block S^{10} is connected to a vertical slide S^{18} by a rod S^{19} formed integral with the slide and connected at its upper end to the block by an interlocking tongue and groove connection S^{20} (Fig. 12). The slide S^{18} is mounted in fixed guides S^{21} , presented by a bracket S^{22} which also presents, at its upper end, an additional guiding element S^{23} for the rod S^{19} . The setting of the slide S^{18} , and consequently the abutment pin block, is determined by a fore-and-aft lever S^{24} fulcrummed near its center and formed at its front end with two pins extending laterally in opposite directions, the pin S^{25} at the right engaging in a slot with which the slide S^{18} is provided, and the pin S^{26} at the left engaging at the top of one or another of a series of stops S^{27} with which the mold magazine L is equipped at its right side (Figs. 11, 12 and 13). These stops are in all respects similar to the stops R^{15} mounted at the left side of the mold magazine and which are used to determine the adjustment of the ejector blade. Likewise as in the case of the stops R^{15} , there is one stop S^{27} provided for each mold in the magazine, and the active stop coop-

erating with the lever S^{24} is the one which corresponds to the mold in transfer position or in the mold holder. The stops are adjustable vertically to different positions wherein they are held by spring actuated detents S^{28} engaging in notches S^{29} in the right side wall of the magazine (Figs. 15 and 16). The only difference is that the various notches S^{29} are spaced according to the different point sizes of the molds. For instance, if the mold in a given magazine pocket has a mold slot to cast a 48 point slug, the stop S^{27} corresponding to that mold is adjusted so that its associated detent S^{28} engages in the topmost notch. Or, if the mold is to cast a 5 point slug, the associated stop is adjusted so that its detent engages the bottom notch. And, for molds having slot widths to cast slugs of intermediate point sizes, the corresponding stops are adjusted accordingly. The lever S^{24} is held in engagement with the active stop S^{27} by a tension spring S^{30} connected to the lever at its front end and anchored to a fixed portion of the machine. As a result of this arrangement, the vertical adjustment of the abutment pin block S^{10} depends directly upon the height or level of the active stop S^{27} . Since, in its different positions of adjustment, the abutment pin block S^{10} presents pins S^9 arranged to provide different knife spacings, any desired spacing can be obtained by properly locating the stop S^{27} , and these stops S^{27} are located so that the knife spacing as determined by the pins S^9 will accord with the slot width of the mold with which the stops S^{27} respectively correspond.

The knives having been adjusted to their minimum spacing by the movement of the control handle O from position 2 to position 3 (Fig. 1), clearance is provided between the pins S^9 and the abutments S^8 on the righthand knife frame sufficient to permit the vertical adjustment of the slide S^{10} . The latter adjustment takes place during the movement of the control handle O from position 3 to position 4 and then back to position 3.

When the handle O is moved from position 3 to position 4, it will be recalled that air is admitted to the top of cylinder L^{20} , thereby causing the piston therein to move downwardly and swing the lever L^{18} of that mechanism in a clockwise direction, looking at the parts from the left. That movement of the lever L^{18} causes an arm s , formed integrally with the lever and which is similar to the arm r through which the ejector blade is adjusted but offset in the opposite direction, to engage a laterally extending lug s^1 formed at the rear end of the lever S^{24} (Fig. 8). As a result, the lever S^{24} is swung in a counterclockwise direction, looking at the parts from the left, to raise the front end thereof to a position wherein the pin S^{26} will be above the level of the topmost stop S^{27} . Thereupon, the mold magazine is adjusted to bring a newly selected mold into the transfer position, which, of course, will locate the stop S^{27} corresponding thereto in a position to be engaged by the lever S^{24} when the latter is swung in a clockwise direction. The clockwise swinging movement of the lever S^{24} is effected by the tension spring S^{30} and is permitted by the arm s when the latter is swung upwardly to its normal position by the introduction of air into the lower end of the cylinder L^{20} as the control handle O is moved back from position 4 to position 3.

Since the abutment pin block S^{10} is adjusted in accordance with the position of the lever S^{24} , it follows that the pin S^9 rendered active by such adjustment will properly space the knives to con-

form with the width of the slot in the selected mold when the righthand knife frame is moved into banking engagement with the pin.

After the abutment pin block S^{10} has been adjusted in the manner just described, the next movement of the control handle O is from position 3 to position 2, causing the fore-and-aft shaft N^8 to be rocked back to normal position in the manner previously described. The return movement of the rock shaft N^8 lowers the vertical rod S^{12} , through which the knife frame S^1 is actuated, thereby permitting the knife frame to move to the right under the action of the compression spring S^5 until it is arrested by its engagement with the active abutment pin S^9 (Fig. 19). This setting is not disturbed by the final movement of the control handle O from position 2 to position 1 because the downward movement of the piston in the transfer slide operating cylinder L^{20} , at this time, is arrested by the banking of the transfer slide upon the locking bar L^{14} .

Automatic safety control

It has been mentioned previously that should the mold fail to reach its proper position in the mold holder during mold substitution, the operator will be apprised of that fact by his inability to shift the control handle O from position 3 to position 2, which in turn is caused by some obstruction blocking the movement of the transverse rod O^6 to its normal leftmost position. However, even though the operator is made aware of the obstruction, there is the possibility that he might inadvertently attempt to start the machine with consequent damage to the parts. Accordingly, the machine is equipped with an automatic safety device which prevents starting the machine in the event the rod O^6 fails to return to its normal leftmost position after the substitution of a magazine. As shown in Fig. 40, the automatic safety device includes a collar o pinned on the rod O^6 and which, in the normal position of said rod, stands clear of a fore-and-aft rod o^1 located in the same horizontal plane as the rod O^6 . The rod o^1 controls a clutch (not shown) by which the machine cycle is inaugurated. When the machine is at rest, the clutch control rod o^1 stands in the position shown in solid lines, thus providing sufficient clearance for the collar o to pass it at the front to the dotted line position shown when the rod O^6 is shifted to the right during mold substitution. And likewise when the rod O^6 is in its normal leftmost position, there is sufficient clearance between the rod O^6 and the front end of the rod o^1 to permit the latter to be moved forwardly to the dotted line position shown wherein the machine cycle is inaugurated. However, should the rod O^6 fail to return to its normal position during a mold substitution, the collar o will block the forward movement of the clutch control rod o^1 and thus lock the machine against starting.

Operation of main cam shaft

The main cam shaft M , with its various cams already described, is best shown in Figs. 3, 18, 19 and 39. As previously stated, this cam shaft is arranged to make one complete revolution during each machine cycle of operation. While it could be driven directly through a clutch similar to that used on the present commercial machines, it is herein shown as being driven through a worm and wheel mechanism M^{10} operated from a relatively high speed shaft which may be

clutch-controlled. Since the means for inaugurating the casting cycle, and for disconnecting the drive at the conclusion of the casting cycle, form the subject matter of another application intended later to be filed, no further mention of the mechanism will be made here.

Conclusion

It is believed that the operations of the various mechanisms have been sufficiently described under the different headings and that, therefore, any further effort in that direction would be superfluous. However, it should perhaps be stated that, so far as the operator is concerned, all of the various operations, with the exception of the mold selection, are virtually automatic. Thus, in substituting one mold for another, the operator is required only to shift the handle O from one extreme position to the other (which operation incidentally can be performed almost instantaneously and by a very light touch due to the design of the various connections), and then set the mold selecting lever P , with the aid of the indicator alongside, in whatever position is required for the selection of the substitute mold, the handle O being then flipped back to its original position to complete the act of mold substitution. The machine is then ready to carry on its slug casting operations with the mold thus selected until the time arrives when a new mold must be substituted, it being understood that the selection of a new mold for use automatically brings about the corresponding adjustment of the ejector and trimming knives. It goes without saying that, in the normal operation of the machine, all of the various parts are operated automatically and in proper timed relation, the mold being first moved to casting position for the casting of the slug, then restored to its normal vertical position for the ejection of the cast slug, and the ejector acting at the proper time to effect the ejection of the slug from the mold and drive it through the side trimming knives which bring it to the proper point size and deliver it finally into the galley at the front. In the course of these operations the mold is kept clean by automatic wiping mechanism associated with it and the trimming knives also kept free of shavings by an automatic wiping mechanism provided for the purpose.

While the various mechanisms would doubtless have utility in other environments or in association with other mechanisms, they have all actually been designed to cooperate with one another in the peculiar way already described in carrying out the basic principles of the present invention which, as before indicated, contemplates an entirely new type of machine differing radically from the present day machines which have been on the market for so many years.

In the accompanying drawings the invention has been shown merely in preferred form and by way of example, but obviously many variations and modifications may be made therein which will still be comprised within its spirit. It is to be understood, therefore, that the invention is not limited to any specific form or embodiment, except insofar as such limitations are specified in the appended claims.

Having thus described my invention, what I claim is:

1. In a slug casting machine, the combination of a mold holder mounted to swing from a normal vertical ejecting position to a horizontal casting position and return at each casting cycle

of the machine, means for effecting such swinging movements of the holder, and means for moving the holder while in horizontal casting position forwardly and backwardly to carry the mold into and out of contact with a composed line before and after casting, respectively.

2. In a slug casting machine, a mold holder fixed at one end to a rock shaft by which it is swung to and from casting position, in combination with means for shifting the rock shaft axially when the holder is in casting position to move said holder toward and from the composed line before and after casting, respectively.

3. In a slug casting machine, a mold holder fixed at one end to a rock shaft by which it is swung to and from casting position, in combination with means including a motion transmitting connection with the rock shaft through which the swinging movement of the mold is effected and means for shifting the rock shaft axially when the holder is in casting position to move the mold into and out of contact with the composed line without disturbing said connection.

4. A combination according to claim 3, wherein the motion transmitting connection includes a rocker element geared to the rock shaft and movable in opposite directions in swinging the holder to and from its casting position.

5. A combination according to claim 3, wherein the motion transmitting connection includes a rocker element geared to the rock shaft and cam operated in a direction to swing the holder to its casting position and pneumatically operated under the control of said cam to swing the holder from its casting position.

6. In a slug casting machine, the combination of a mold holder mounted to swing from a normal vertical ejecting position to a horizontal casting position and return at each casting cycle of the machine, means for effecting such swinging movements of the holder, means for moving the holder while in horizontal casting position forwardly and backwardly to carry the mold into and out of contact with a composed line before and after casting, respectively, and means to engage the holder as it is moved forwardly to insure the horizontal alignment of the mold slot with the matrix characters of the composed line.

7. In a slug casting machine, the combination of a mold holder mounted to swing from a normal vertical ejecting position to a horizontal casting position and return at each casting cycle of the machine, means for effecting such swinging movements of the holder, means for moving the holder while in horizontal casting position forwardly and backwardly to carry the mold into and out of contact with a composed line before and after casting, respectively, and a stationary lug arranged to engage in a notch formed in the holder as the latter is moved forwardly and insure the horizontal alignment of the mold slot with the matrix characters of the composed line.

8. In a slug casting machine, the combination of a mold holder pivotally mounted at one end to swing from a normal vertical ejecting position to a horizontal casting position and return at each casting cycle of the machine, means for effecting such swinging movements of the holder, and a fixed arcuate-shaped support to engage the free end of the holder in its ejecting position.

9. In a slug casting machine, the combination of a mold holder pivotally mounted at one end to swing from a normal vertical ejecting position to a horizontal casting position and return at each casting cycle of the machine, means for effecting

such swinging movements of the holder, a stationary knife to trim the base of the cast slug as the holder is returned to its ejecting position, and a fixed arcuate-shaped support to engage the free end of the holder during the slug trimming operation.

10. In a slug casting machine, a mold holder pivotally mounted at one end to swing to and from casting position and open at its other end to permit the insertion and removal of the mold in use.

11. In a slug casting machine, a mold holder pivotally mounted at one end to swing to and from casting position and open at its other end to permit the insertion and removal of the mold in use, in combination with releasable means for locking the mold properly within the holder.

12. In a slug casting machine, a mold holder pivotally mounted at one end to swing to and from casting position and open at its other end to permit the insertion and removal of the mold in use, in combination with releasable means for locking the mold both endwise and edgewise within the holder.

13. In a slug casting machine, a mold holder pivotally mounted at one end to swing to and from casting position and open at its other end to permit the insertion and removal of the mold in use, in combination with releasable means for locking the mold endwise in the holder, and other releasable means for locking the mold edgewise in the holder.

14. In a slug casting machine, a mold holder pivotally mounted at one end to swing to and from casting position and open at its other end to permit the insertion and removal of the mold in use, in combination with releasable means for locking the mold properly within the holder and manual connections for releasing the locking means in effecting the removal of the mold, said connections being mounted independently of the holder and arranged to permit the swinging of the holder without interference in the normal operation of the machine.

15. In a slug casting machine, a mold holder fixed at one end to a hollow rock shaft by which it is swung to and from casting position and open at its other end to permit the insertion and removal of the mold in use, in combination with releasable means for locking the mold within the holder, and manual connections for releasing said locking means in effecting the removal of the mold, said connections extending in part through the hollow rock shaft to permit the swinging of the holder without interference in the normal operation of the machine.

16. In a slug casting machine, the combination of a mold holder mounted to swing from a normal vertical ejecting position to a horizontal casting position and return at each casting cycle of the machine, means for effecting such swinging movements of the holder, and means for braking the return movement of the holder as it approaches its vertical ejecting position.

17. In a slug casting machine, the combination of a mold holder mounted to swing from a normal vertical ejecting position to a horizontal casting position and return at each casting cycle of the machine, means for effecting such swinging movements of the holder, and cushioning means to brake the return movement of the holder as it approaches its vertical ejecting position.

18. In a slug casting machine, the combination of a mold holder movable from ejecting to casting position and return at each casting cycle

- of the machine, pneumatically operated means for effecting the movement of the holder in at least one direction, and mechanism driven independently of the pneumatic means for regulating such movement of the holder.
19. In a slug casting machine, the combination of a mold holder movable from ejecting to casting position and return at each casting cycle of the machine, cam means for effecting the movement of the holder in one direction and for regulating its movement in the opposite direction, and pneumatically operated means for effecting such latter movement of the holder.
20. In a slug casting machine, the combination of a mold holder movable from ejecting to casting position and return at each casting cycle of the machine, a stationary knife to trim the base of the cast slug as the holder is returned to its ejecting position, cam actuated means for effecting the movement of the holder from ejecting to casting position, and pneumatically operated means for effecting the movement of the holder from casting to ejecting position against the resistance set up by the slug trimming operation.
21. In a slug casting machine, the combination of a mold holder movable from ejecting to casting position and return at each casting cycle of the machine, pneumatically operated means for effecting the movement of the holder in at least one direction, and a time controlled valve governing the operation of said pneumatically operated means.
22. In a slug casting machine, the combination of a mold holder open at one end to permit the endwise insertion and removal of the mold in use, and a latch member mounted in the mold holder and adapted to engage means on the mold to lock and position the mold endwise in the holder.
23. In a slug casting machine, the combination of a mold holder open at one end to permit the endwise insertion and removal of the mold in use, a latch member mounted in the mold holder and adapted to engage means on the mold to lock the mold endwise in the holder, and positive connections controlled from a point at the front of the machine, remote from the mold holder, for disengaging the latch when the removal of the mold is desired.
24. In a slug casting machine, the combination of a mold holder having two fixed side members to accommodate a mold between them and being open at one end to permit the endwise insertion and removal of the mold in use, and means adapted to react between one of said side members and an adjacent edge of the mold to force the mold tightly against the other side member whereby the mold is positioned and locked edgewise in the holder.
25. In a slug casting machine, the combination of a mold holder having two fixed side members to accommodate a mold between them and being open at one end to permit the endwise insertion and removal of the mold in use, a cam journaled in one side member of the holder and presenting an eccentric edge adapted to engage the edge of the mold adjacent said member, and devices for rotating the cam, said cam being adapted when rotated in one direction to force the mold tightly against the other side member of the holder, whereby the mold is positioned and locked edgewise in the holder, and when rotated in the opposite direction to free the mold for removal from the holder.
26. In a slug casting machine, the combination of a mold holder having two fixed side members to accommodate a mold between them and being open at one end to permit the endwise insertion and removal of the mold in use, a cam journaled in one side member of the holder and presenting an eccentric edge adapted to engage the edge of the mold adjacent said member, and devices for rotating the cam in opposite directions to operative and inoperative positions, respectively, said devices comprising a pinion connected to the cam, a rack bar slidable longitudinally in the holder and meshing with the cam pinion, and means for sliding the rack bar in opposite directions in rotating the cam.
27. In a slug casting machine, the combination of a mold holder including two fixed side members to accommodate a mold between them and being open at one end to permit the endwise insertion and removal of the mold in use, a latch device mounted in the mold holder and adapted when operative to engage means on the mold to lock the mold endwise in the holder, a cam device journaled in one side member of the holder and adapted when operative to engage the edge of the mold adjacent said member to force the mold tightly against the other side member of the holder to position and lock the mold edgewise in the holder, and common means for rendering said latch and cam devices inoperative when the removal of a mold is desired and operative when a mold is in use.
28. In a slug casting machine, the combination of a mold holder, a storage magazine containing a series of molds and movable to bring any selected mold into alignment with the holder, and power operated means for transferring the selected mold from the magazine to the holder and vice versa.
29. In a slug casting machine, the combination of a mold holder, a storage magazine containing a series of molds and movable to bring any selected mold into alignment with the holder, and pneumatically operated means for transferring the selected mold from the magazine to the holder and vice versa.
30. In a slug casting machine, the combination of a mold holder open at one end, a storage magazine formed with mold containing pockets open at the end adjacent the mold holder, said magazine being movable to bring any selected mold pocket into alignment with the mold holder, and a reciprocable slide operable to transfer the selected mold from the magazine to the holder and vice versa.
31. In a slug casting machine, the combination of a mold holder open at one end, a storage magazine formed with mold containing pockets open at the end adjacent the mold holder, said magazine being movable to bring any selected mold pocket into alignment with the mold holder, and a pneumatically operated reciprocable slide for transferring the selected mold endwise from the magazine to the holder and vice versa.
32. A combination according to claim 30, wherein the transfer slide is formed to connect with each selected mold so as to move it positively in both directions.
33. A combination according to claim 30, wherein the transfer slide is maintained in its operated position after transferring the selected mold to the holder, thus preventing the movement of the magazine until said mold is first restored thereto.
34. A combination according to claim 30,

wherein the transfer slide is formed to connect with each selected mold so as to move it positively in both directions and is maintained in its operated position after transferring the selected mold to the holder, characterized in that the form of connection between the transfer slide and the mold is such as not to interfere with the swinging of the mold holder during the normal operation of the machine.

35. A combination according to claim 30, wherein the transfer slide is maintained in a position clear of the magazine after being operated to transfer the selected mold from the holder to the magazine, thus permitting the free movement of the magazine when all the molds are stored therein.

36. A combination according to claim 50, wherein the transfer slide is formed to connect with each selected magazine so as to move it positively in both directions and is maintained in a position clear of the magazine after being operated to transfer the selected mold from the holder to the magazine, characterized in that the form of connection between the transfer slide and mold is such as not to interfere with the free movement of the magazine under such conditions.

37. In a slug casting machine, the combination of a mold holder open at one end, a storage magazine formed with mold containing pockets open at the end adjacent the mold holder, said magazine being movable to bring any selected mold pocket into alignment with the mold holder, a reciprocable slide operable to transfer the selected mold from the magazine to the holder and vice versa, and means, controllable at will from the front of the machine, for actuating said slide to effect one transfer operation or the other, as desired.

38. In a slug casting machine, the combination of a mold holder open at one end, a storage magazine formed with mold containing pockets open at the end adjacent the mold holder, said magazine being movable to bring any selected mold pocket into alignment with the mold holder, a pneumatically operated reciprocable slide for transferring the selected mold endwise from the magazine to the holder and vice versa, and a valve having a hand control arranged within easy reach of the operator while seated at the keyboard of the machine for governing the operation of said pneumatically operated transfer slide.

39. In a slug casting machine, the combination of a mold holder, a storage magazine containing a series of molds and movable to bring any selected mold into alignment with the holder, means controllable at will from the front of the machine for effecting such movement of the magazine, and means likewise controllable at will from the front of the machine for transferring the selected mold from the magazine to the holder and vice versa.

40. A combination according to claim 39, characterized in that the magazine moving means are locked against operation whenever a mold is contained in the mold holder.

41. In a slug casting machine, the combination of a mold holder pivotally mounted at one end to swing from a normal vertical ejecting position to a horizontal casting position and return at each casting cycle of the machine, said holder being open at its free end to permit the endwise insertion and removal of a mold, and a storage magazine containing a series of vertically disposed molds arranged one behind another in a fore-and-aft direction, said magazine being mov-

able forwardly and backwardly to bring any selected mold into vertical alignment with the holder when the latter occupies its normal position, whereby said mold may be transferred from the magazine to the holder and vice versa, as required.

42. In a slug casting machine, the combination of a mold holder pivotally mounted at one end to swing upwardly from a normal vertical ejecting position to a horizontal casting position and return at each casting cycle of the machine, said holder being open at its free end to permit the endwise insertion and removal of a mold, and a storage magazine disposed below the level of the mold holder and containing a series of vertically disposed molds arranged one behind another in a fore-and-aft direction, said magazine being slidable forwardly and backwardly to bring any selected mold into vertical alignment with the overlying holder when the latter occupies its normal position.

43. In a slug casting machine, the combination of a mold holder pivotally mounted at one end to swing upwardly from a normal vertical ejecting position to a horizontal casting position and return at each casting cycle of the machine, said holder being open at its free end to permit the endwise insertion and removal of a mold, a storage magazine disposed below the level of the mold holder and containing a series of vertically disposed molds arranged one behind another in a fore-and-aft direction, said magazine being slidable forwardly and backwardly to bring any selected mold into vertical alignment with the overlying holder when the latter occupies its normal position, and a vertically movable slide supported beneath the magazine and arranged in line with the holder, said slide being operable to lift the selected mold from the magazine into the holder as well as to lower it from the holder into the magazine.

44. In a slug casting machine, the combination of a mold holder pivotally mounted at one end to swing upwardly from a normal vertical ejecting position to a horizontal casting position and return at each casting cycle of the machine, said holder being open at its free end to permit the endwise insertion and removal of a mold, and a storage magazine disposed below the level of the mold holder and containing a series of vertically disposed molds arranged one behind another in a fore-and-aft direction, said magazine being slidable forwardly and backwardly to bring any selected mold into vertical alignment with the overlying holder when the latter occupies its normal position, a vertically movable slide supported beneath the magazine and arranged in line with the holder, said slide being operable to lift the selected mold from the magazine into the holder as well as to lower it from the holder into the magazine, releasable locking means carried by the mold holder for confining the mold therein, and common means, operable from the front of the machine, for releasing said locking means and for controlling the operation of the transfer slide in lowering the mold from the holder into the magazine.

45. In a slug casting machine, the combination of a mold holder pivotally mounted at one end to swing upwardly from a normal vertical ejecting position to a horizontal casting position and return at each casting cycle of the machine, said holder being open at its free end to permit the endwise insertion and removal of a mold, and a storage magazine disposed below the level of the mold holder and containing a series of verti-

cally disposed molds arranged one behind another in a fore-and-aft direction, said magazine being slidable forwardly and backwardly to bring any selected mold into vertical alignment with the overlying holder when the latter occupies its normal position, a vertically movable slide supported beneath the magazine and arranged in line with the holder, said slide being operable to lift the selected mold from the magazine into the holder as well as to lower it from the holder into the magazine, releasable locking means carried by the mold holder for confining the mold therein, and common means, operable from the front of the machine, for releasing said locking means and for controlling the operation of the transfer slide in lowering the mold from the holder into the magazine, said common means serving also to control the subsequent operation of the transfer slide in lifting a newly selected mold from the magazine into the holder as well as the subsequent operation of the locking means in confining said mold in the holder.

46. In a slug casting machine, the combination of a mold holder pivotally mounted at one end to swing upwardly from a normal vertical ejecting position to a horizontal casting position and return at each casting cycle of the machine, said holder being open at its free end to permit the endwise insertion and removal of a mold, and a storage magazine disposed below the level of the mold holder and containing a series of vertically disposed molds arranged one behind another in a fore-and-aft direction, said magazine being slidable forwardly and backwardly to bring any selected mold into vertical alignment with the overlying holder when the latter occupies its normal position, a vertically movable slide supported beneath the magazine and arranged in line with the holder, said slide being operable to lift the selected mold from the magazine into the holder as well as to lower it from the holder into the magazine, releasable means carried by the mold holder for locking the mold endwise therein, other releasable means also carried by the holder for locking the mold edgewise therein, and common means, operable from the front of the machine, for releasing both said locking means and for controlling the operation of the transfer slide in lowering the freed mold from the holder into the magazine, said common means also serving to control the subsequent operation of the transfer slide in lifting a newly selected mold from the magazine into the holder as well as the subsequent operation of the two locking means in confining said mold in the holder.

47. In a slug casting machine, the combination of a mold holder open at one end, a storage magazine formed with mold containing pockets open at the end adjacent the mold holder, said magazine being movable to bring any selected mold pocket into alignment with the mold holder, a reciprocable slide operable positively to move the selected mold in one direction out of the magazine into the holder and vice versa, and a lock for maintaining the slide in its operated position after the selected mold has been transferred to the holder.

48. In a slug casting machine, the combination of a mold holder open at one end, a storage magazine formed with mold containing pockets open at the end adjacent the mold holder, said magazine being movable to bring any selected mold pocket into alignment with the mold holder, a reciprocable slide operable positively to move

5 the selected mold in one direction out of the magazine into the holder and vice versa, pneumatic means for operating said slide in both directions, and a lock for maintaining the slide in its operated position after the selected mold has been transferred to the holder.

49. A combination according to claim 48 wherein the pneumatic means is equipped with a control valve and wherein there are provided means operable from the front of the machine for conjointly releasing the lock and operating the valve to effect movement of the mold from the holder into the magazine by the pneumatically operated slide and subsequently for conjointly operating the valve to effect movement of a newly selected mold into the holder and restoring the lock.

50. In a slug casting machine, the combination of a mold holder pivotally mounted at one end to swing upwardly from a normal vertical ejecting position to a horizontal casting position and return at each casting cycle of the machine, said holder being open at its free end to permit the endwise insertion and removal of a mold, and a storage magazine disposed below the level of the mold holder and containing a series of vertically disposed molds arranged one behind another in a fore-and-aft direction, said magazine being slidable forwardly and backwardly to bring any selected mold into vertical alignment with the overlying holder when the latter occupies its normal position, a vertically movable slide supported beneath the magazine and arranged in line with the holder, said slide being operable to lift the selected mold from the magazine into the holder as well as to lower it from the holder into the magazine, a lock for maintaining the slide in its raised position, releasable locking means carried by the mold holder for confining the mold therein, and common means, operable from the front of the machine, for rendering the slide lock and the mold locking means inoperative and for controlling the operation of the transfer slide in lowering the mold from the holder into the magazine.

51. In a slug casting machine, the combination of a mold holder pivotally mounted at one end to swing upwardly from a normal vertical ejecting position to a horizontal casting position and return at each casting cycle of the machine, said holder being open at its free end to permit the endwise insertion and removal of a mold, and a storage magazine disposed below the level of the mold holder and containing a series of vertically disposed molds arranged one behind another in a fore-and-aft direction, said magazine being slidable forwardly and backwardly to bring any selected mold into vertical alignment with the overlying holder when the latter occupies its normal position, a vertically movable slide supported beneath the magazine and arranged in line with the holder, said slide being operable to lift the selected mold from the magazine into the holder as well as to lower it from the holder into the magazine, a lock for maintaining the slide in its raised position, releasable locking means carried by the mold holder for confining the mold therein, and common means, operable from the front of the machine, for rendering the slide lock and the mold locking means inoperative and for controlling the operation of the transfer slide in lowering the mold from the holder into the magazine, said common means serving also to control the subsequent operation of the transfer slide in lift-

ing a newly selected mold from the magazine into the holder and to render operative the slide lock and the mold locking means.

52. A combination according to claim 50 where-
in the vertically movable slide is pneumatically
operated under the control of a valve actuated by
the common means at the front of the machine.

53. In a slug casting machine equipped with a
mold holder and a series of molds contained in a
mold magazine which is adjustable to bring any
selected mold into a position for transfer to and
from the mold holder, the combination of a mold
magazine adjusting device settable differently ac-
cording to the mold selected, and intermediate
connections for moving the mold magazine to 15
bring that mold into the transfer position for
which the adjusting device is set.

54. A combination according to claim 53 where-
in the intermediate connections are breakable to
permit the mold magazine to be removed from the 20
machine.

55. A combination according to claim 53 where-
in the intermediate connections are breakable to
permit the mold magazine to be removed from the
machine, and wherein means are provided for in-
suring that the magazine adjustments correspond
to the settings of the adjusting device when the
connections are restored upon the replacement
of the magazine in the machine.

56. In a slug casting machine equipped with an 30
ejector mechanism adjustable as to blade width,
the combination of a mold holder, a storage mag-
azine containing a series of molds, means for
transferring any selected mold from the maga-
zine to the holder, and automatic means for ad-
justing the blade width of the ejector mechanism
to correspond with the slot length of the selected
mold.

57. In a slug casting machine equipped with an 40
ejector mechanism adjustable as to blade width,
the combination of a mold holder, a storage mag-
azine containing a series of molds and movable to
bring any selected mold into alignment with the
holder, whereby said mold may be transferred
from the magazine to the holder and vice versa,
and automatic means for adjusting the blade 45
width of the ejector mechanism to correspond
with the slot length of the selected mold when
transferred from the magazine to the holder.

58. In a slug casting machine equipped with an 50
ejector mechanism adjustable as to blade width,
the combination of a mold holder, a storage mag-
azine containing a series of molds and movable to
bring any selected mold into alignment with the
holder, means for transferring the selected mold
from the magazine to the holder and vice versa,
and means acting as the selected mold is trans-
ferred from the magazine to the holder for ad-
justing the blade width of the ejector mechanism
to correspond with the slot length of said mold.

59. In a slug casting machine equipped with an
ejector mechanism adjustable as to blade width,
the combination of a mold holder, a storage mag-
azine containing a series of molds and movable to
bring any selected mold into alignment with the
holder, means for transferring the selected mold
from the magazine to the holder and vice versa,
and means acting as the selected mold is trans-
ferred from the magazine to the holder for ad-
justing the blade width of the ejector mechanism
to correspond with the slot length of said mold,
said adjusting means acting as said mold is sub-
sequently transferred from the holder to the mag-
azine to restore the ejector mechanism to a neu-
tral setting.

60. In a slug casting machine equipped with an
ejector mechanism adjustable as to blade width
and with a shiftable element to effect such ad-
justment of the ejector mechanism, the combina-
tion of a mold holder, a storage magazine con-
taining a series of molds and movable to bring
any selected mold into alignment with the holder,
means for transferring the selected mold from
the magazine to the holder and vice versa, means
controlled by such transfer movement of the se-
lected mold for shifting the ejector adjusting ele-
ment from a given starting position to the final
position required, and means brought into play
by the mold selecting movement of the storage
magazine for determining said final position of
the ejector adjusting element.

61. In a slug casting machine equipped with an
ejector mechanism adjustable as to blade width
and with a shiftable element to effect such ad-
justment of the ejector mechanism, the combina-
tion of a mold holder, a storage magazine con-
taining a series of molds and movable to bring
any selected mold into alignment with the holder,
means for transferring the selected mold from
the magazine to the holder and vice versa, means
controlled by such transfer movement of the se-
lected mold for shifting the ejector adjusting ele-
ment from a given starting position to the final
position required, and means brought into play
by the mold selecting movement of the stor-
age magazine for determining said final position
of the ejector adjusting element, said ejector ad-
justing element being shifted back to its given
starting position as the selected mold is sub-
sequently transferred from the holder to the maga-
zine.

62. A combination according to claim 60,
wherein the means for determining the final
position of the ejector adjusting element include
a series of stop devices carried by the magazine,
one for each mold, said stop devices being set
in positions appropriate to the slot lengths of
their corresponding molds.

63. A combination according to claim 60,
wherein the means for determining the final posi-
tion of the ejector adjusting element include a
series of stop devices carried by the magazine,
one for each mold, said stop devices being set
in positions appropriate to the slot lengths of
their corresponding molds, and wherein said stop
devices are each adjustable to different positions
on the magazine to accommodate different ar-
rangements of molds in the magazine.

64. In a slug casting machine equipped with an
ejector mechanism adjustable as to blade width
and with a shiftable element to effect such ad-
justment of the ejector mechanism, the combina-
tion of a mold holder open at one end, a
storage magazine formed with mold containing
pockets open at the end adjacent the mold hold-
er, said magazine being movable to bring any
selected mold pocket into alignment with the
mold holder, a reciprocable slide operable to
transfer the selected mold endwise from the
magazine to the holder and vice versa, means
whereby said element is shifted from a given
starting position to the final position required
as the selected mold is transferred from the
magazine to the holder and later restored to its
given starting position as said mold is subse-
quently transferred from the holder to the magazine,
and a series of stops carried by the magazine,
one for each mold, to determine the final position
of the ejector adjusting element in accordance
with the mold selected.

65. A combination according to claim 64, characterized in that the reciprocable slide for transferring the selected mold from the magazine to the holder and vice versa is operated by pneumatically operated means under the control of a valve operable manually from the front of the machine.
66. In a slug casting machine, the combination of an ejector mechanism adjustable as to blade width, and pneumatically operated means for effecting such adjustment of the ejector mechanism.
67. In a slug casting machine, the combination of an ejector mechanism comprising a main actuating slide and a series of blade sections arranged in superposed edge to edge relation, a shiftable element to connect any selected number of blade sections to the main actuating slide so as thus to vary the blade width of the ejector mechanism, and pneumatically operated means for shifting said connecting element.
68. In a slug casting machine, the combination of an ejector mechanism comprising a main actuating slide and a series of blade sections arranged in superposed edge to edge relation, a shiftable element to connect any selected number of blade sections to the main actuating slide so as thus to vary the blade width of the ejector mechanism, pneumatically operated means for shifting said connecting element, and a valve having a hand control located at the front of the machine for controlling the operation of said pneumatically operated means.
69. In a slug casting machine equipped with an ejector mechanism comprising a main actuating slide and a series of blade sections arranged in superposed edge to edge relation and with a shiftable element to connect any selected number of blade sections to the main actuating slide so as thus to vary the blade width of the ejector mechanism, the combination of a mold holder, a storage magazine containing a series of molds and movable to bring any selected mold into alignment with the holder, means for transferring the selected mold from the magazine to the holder and vice versa, and means controlled by the transfer of the selected mold from the magazine to the holder for shifting the ejector connecting element from a given starting position to the final position required in adjusting the blade width of the ejector mechanism to correspond with the slot length of the selected mold, and means brought into play by the mold selecting movement of the storage magazine for determining said final position of the ejector connecting element.
70. In a slug casting machine equipped with a slug trimming mechanism adjustable to accommodate slugs of different thicknesses, the combination of a mold holder, a storage magazine containing a series of molds, means for transferring any selected mold from the magazine to the holder, and automatic means for adjusting the slug trimming mechanism to correspond with the slot width of the selected mold.
71. In a slug casting machine equipped with a slug trimming mechanism adjustable to accommodate slugs of different thicknesses, the combination of a mold holder, a storage magazine containing a series of molds and movable to bring any selected mold into alignment with the holder, whereby said mold may be transferred from the magazine to the holder and vice versa, and automatic means for adjusting the slug trimming mechanism to correspond with the slot width of the selected mold.
72. In a slug casting machine equipped with a slug trimming mechanism adjustable to accommodate slugs of different thicknesses, the combination of a mold holder, a storage magazine containing a series of molds and movable to bring any selected mold into alignment with the holder, means for transferring the selected mold from the magazine to the holder and vice versa, and means acting as the selected mold is transferred from the magazine to the holder for adjusting the slug trimming mechanism to correspond with the slot width of said mold.
73. In a slug casting machine equipped with a slug trimming mechanism adjustable to accommodate slugs of different thicknesses, the combination of a mold holder, a storage magazine containing a series of molds and movable to bring any selected mold into alignment with the holder, means for transferring the selected mold from the magazine to the holder and vice versa, and means acting as the selected mold is transferred from the magazine to the holder for adjusting the slug trimming mechanism to correspond with the slot width of said mold, said adjusting means acting as said mold is subsequently transferred from the holder to the magazine for restoring the slug trimming mechanism to a neutral setting.
74. In a slug casting machine equipped with a slug trimming mechanism adjustable to accommodate slugs of different thicknesses and with a shiftable element to effect such adjustment of the slug trimming mechanism, the combination of a mold holder, a storage magazine containing a series of molds and movable to bring any selected mold into alignment with the holder, means for transferring the selected mold from the magazine to the holder and vice versa, means controlled by the transfer movement of the selected mold from the magazine to the holder for shifting the slug trimming mechanism adjusting element from a given starting position to the final position required, and means brought into play by the mold selecting movement of the storage magazine for determining said final position of said adjusting element.
75. In a slug casting machine equipped with a slug trimming mechanism adjustable to accommodate slugs of different thicknesses and with a shiftable element to effect such adjustment of the slug trimming mechanism, the combination of a mold holder, a storage magazine containing a series of molds and movable to bring any selected mold into alignment with the holder, means for transferring the selected mold from the magazine to the holder and vice versa, means controlled by the transfer movement of the selected mold from the magazine to the holder for shifting the slug trimming mechanism adjusting element from a given starting position to the final position required, and means brought into play by the mold selecting movement of the storage magazine for determining said final position of said adjusting element, said adjusting element being shifted back to its given starting position as the selected mold is subsequently transferred from the holder to the magazine.
76. A combination according to claim 74, where-in the means for determining the final position of the slug trimming mechanism adjusting element include a series of stop devices carried by the magazine, one for each mold, said stop devices being set in position appropriate to the slot widths of their corresponding molds.

77. A combination according to claim 74, where-
in the means for determining the final position of
the slug trimming mechanism adjusting element
include a series of stop devices carried by the
magazine, one for each mold, said stop devices
being set in position appropriate to the slot widths
of their corresponding molds, and wherein said
stop devices are each adjustable to different posi-
tions on the magazine to accommodate different
arrangements of molds in the magazine.

78. In a slug casting machine equipped with a
pair of slug trimming knives, one adjustable rela-
tively to the other to accommodate slugs of dif-
ferent thicknesses, and with a shiftable element
to effect such adjustment of the trimming knife,
the combination of a mold holder, a storage maga-
zine containing a series of molds and movable to
bring any selected mold into alignment with the
holder, means for transferring the selected mold
from the magazine to the holder and vice versa,
means controlled by the transfer of the selected
mold from the magazine to the holder for shift-
ing the knife adjusting element from a given
starting position to the final position required in
adjusting the knives to correspond with the slot
width of the selected mold, and means brought
into play by the mold selecting movement of the
storage magazine for determining said final posi-
tion of the knife adjusting element.

79. In a slug casting machine equipped with a
pair of slug trimming knives, one adjustable rela-
tively to the other to accommodate slugs of dif-
ferent thicknesses and with a shiftable element
to effect such adjustment of the trimming knife,
the combination of a mold holder open at one end,
a storage magazine formed with mold containing
pockets open at the end adjacent the mold holder,
said magazine being movable to bring any selected
mold pocket into alignment with the mold holder,
a reciprocable slide operable to transfer the
selected mold endwise from the magazine to the
holder and vice versa, means whereby said ele-
ment is shifted from a given starting position to
the final position required as the selected mold is
transferred from the magazine to the holder and
whereby said element is later restored to its given
starting position as said mold is subsequently
transferred from the holder to the magazine, and
a series of stops carried by the magazine, one for
each mold, to determine the final position of the
knife adjusting element in accordance with the
slot width of the mold selected.

80. A combination according to claim 79, char-
acterized in that the reciprocable slide for trans-
ferring the selected mold from the magazine to
the holder and vice versa is operated by pneu-
matically operated means under the control of
a valve operable manually from the front of the
machine.

81. In a slug casting machine, the combination
of slug trimming mechanism adjustable to ac-
commodate slugs of different thicknesses, and
pneumatically operated means for effecting such
adjustment of the slug trimming mechanism.

82. In a slug casting machine, the combination
of a pair of slug trimming knives, one adjustable
relatively to the other to accommodate slugs of
different thicknesses, a shiftable element to effect
such adjustment of the slug trimming knife, and
pneumatically operated means for shifting said
element.

83. In a slug casting machine, the combination
of a pair of slug trimming knives, one adjustable
relatively to the other to accommodate slugs of
different thicknesses, a shiftable element to effect

such adjustment of the slug trimming knife,
pneumatically operated means for shifting said
element, and a valve having a hand control lo-
cated at the front of the machine for controlling
the operation of said pneumatically operated
means.

84. In a slug casting machine equipped with an
ejector mechanism adjustable as to blade width
as well as a slug trimming mechanism adjustable
to accommodate slugs of different thicknesses,
the combination of a mold holder, a storage
magazine containing a series of molds, means for
transferring any selected mold from the maga-
zine to the holder, and automatic means for ad-
justing the blade width of the ejector mechanism
to correspond with the slot length of the selected
mold and for simultaneously adjusting the slug
trimming mechanism to correspond with the slot
width of said mold.

85. In a slug casting machine equipped with
an ejector mechanism adjustable as to blade
width as well as with a slug trimming mechanism
adjustable to accommodate slugs of different
thicknesses, the combination of a mold holder, a
storage magazine containing a series of molds
and movable to bring any selected mold into
alignment with the holder, whereby said mold
may be transferred from the magazine to the
holder and vice versa, and automatic means for
adjusting the blade width of the ejector mech-
anism to correspond with the slot length of the
selected mold when transferred from the maga-
zine to the holder and for simultaneously adjust-
ing the slug trimming mechanism to correspond
with the slot width of said selected mold.

86. In a slug casting machine equipped with
an ejector mechanism adjustable as to blade
width as well as with a slug trimming mechanism
adjustable to accommodate slugs of different
thicknesses, the combination of a mold holder,
a storage magazine containing a series of molds
and movable to bring any selected mold into
alignment with the holder, means for trans-
ferring the selected mold from the magazine to the
holder and vice versa, and means controlled by
the transfer of the selected mold from the maga-
zine to the holder for adjusting the blade width
of the ejector mechanism to correspond with the
slot length of said mold and for simultaneously
adjusting the slug trimming mechanism to cor-
respond with the slot width of said mold.

87. In a slug casting machine equipped with
an ejector mechanism adjustable as to blade
width as well as with a slug trimming mechanism
adjustable to accommodate slugs of different
thicknesses, the combination of a mold holder, a
storage magazine containing a series of molds
and movable to bring any selected mold into
alignment with the holder, means for trans-
ferring the selected mold from the magazine to the
holder and vice versa, and means controlled by
the transfer of the selected mold from the maga-
zine to the holder for adjusting the blade width
of the ejector mechanism to correspond with
the slot length of said mold and for simultane-
ously adjusting the slug trimming mechanism to
correspond with the slot width of said mold, said
adjusting means being actuated as said mold
is subsequently transferred from the holder to
the magazine to restore the ejector mechanism
and the slug trimming mechanism to a neutral
setting.

88. In a slug casting machine equipped with
an ejector mechanism adjustable as to blade
width and a shiftable element to effect such ad-

justment of the ejector mechanism as well as with a slug trimming mechanism adjustable to accommodate slugs of different thicknesses and a shiftable element to effect such adjustment of the slug trimming mechanism, the combination of a mold holder, a storage magazine containing a series of molds and movable to bring any selected mold into alignment with the holder, means for transferring the selected mold from the magazine to the holder and vice versa, means controlled by the transfer movement of the selected mold from the magazine to the holder for simultaneously shifting the ejector adjusting element and the slug trimming mechanism adjusting element from given starting positions to the final positions required, and means brought into play by the mold selecting movement of the storage magazine for determining said final positions of the two said adjusting elements.

89. A combination according to claim 88, wherein the means for determining the final positions of the ejector adjusting element and the slug trimming mechanism adjusting element include two series of stop devices carried by the magazine, two for each mold, said stop devices being set in positions appropriate to the slot lengths and slot widths of their corresponding molds respectively.

90. A combination according to claim 88, wherein the means for determining the final positions of the ejector adjusting element and the slug trimming mechanism adjusting element include two series of stop devices carried by the magazine, two for each mold, said stop devices being set in positions appropriate to the slot lengths and slot widths of their corresponding molds respectively, and wherein said stop devices are each adjustable to different positions on the magazine to accommodate different arrangements of molds in the magazine.

91. In a slug casting machine equipped with an ejector mechanism comprising a main actuating slide, a series of blade sections arranged in superposed edge to edge relation, and a shiftable element to connect any selected number of blade sections to the main actuating slide so as thus to vary the blade width of the ejector mechanism, as well as with a pair of slug trimming knives, one adjustable relatively to the other, and a shiftable element to effect such adjustment of the trimming knife, the combination of a mold holder, a storage magazine containing a series of molds and movable to bring any selected mold into alignment with the holder, means for transferring the selected mold from the magazine to the holder and vice versa, means controlled by the transfer of the selected mold from the magazine to the holder for shifting the ejector connecting element and the knife adjusting element from given starting positions to the final positions required in adjusting the ejector mechanism and slug trimming knives to correspond with the slot length and slot width of the selected mold, and means brought into play by the mold selecting movement of the storage magazine for determining said final positions of the ejector connecting element and the knife adjusting element.

92. In a slug casting machine equipped with an ejector mechanism comprising a main actuating slide, a series of blade sections arranged in superposed edge to edge relation, and a shiftable element to connect any selected number of blade sections to the main actuating slide so as thus to vary the blade width of the ejector mech-

anism, as well as with a pair of slug trimming knives, one adjustable relatively to the other, and a shiftable element to effect such adjustment of the trimming knife, the combination of a mold holder open at one end, a storage magazine formed with mold containing pockets open at the end adjacent the mold holder, said magazine being movable to bring any selected mold pocket into alignment with the mold holder, a reciprocable slide operable to transfer the selected mold endwise from the magazine to the holder and vice versa, means whereby the ejector connecting element and the knife adjusting element are shifted simultaneously from given starting positions to the final positions required as the selected mold is transferred from the magazine to the holder and whereby said elements are later restored to their given starting positions as said mold is subsequently transferred from the holder to the magazine, and two series of stops carried by the magazine, two for each mold, to determine the final positions of the ejector connecting element and the knife adjusting element in accordance with the slot length and slot width of the mold selected.

93. A combination according to claim 92, characterized in that the reciprocable slide for transferring the selected mold from the magazine to the holder and vice versa is operated by pneumatically operated means under the control of a valve operable manually from the front of the machine.

94. In a slug casting machine, the combination of an ejector mechanism adjustable as to blade width to accommodate slugs of different lengths, a slug trimming mechanism adjustable to accommodate slugs of different thicknesses, and common pneumatically operated means for effecting such adjustment of the two said mechanisms.

95. In a slug casting machine, the combination with an ejector mechanism comprising a main actuating slide, a series of blade sections arranged in superposed edge to edge relation, a shiftable element to connect any selected number of blade sections to the main actuating slide so as thus to vary the blade width of the ejector mechanism, and with a pair of slug trimming knives, one adjustable relatively to the other to accommodate slugs of different thicknesses and a shiftable element to effect such adjustment of the trimming knife, of common pneumatically operated means for shifting both said elements.

96. In a slug casting machine, the combination with an ejector mechanism comprising a main actuating slide, a series of blade sections arranged in superposed edge to edge relation, a shiftable element to connect any selected number of blade sections to the main actuating slide so as thus to vary the blade width of the ejector mechanism, and with a pair of slug trimming knives, one adjustable relatively to the other to accommodate slugs of different thicknesses and a shiftable element to effect such adjustment of the trimming knife, of common pneumatically operated means for shifting both said elements, and a valve controlled by hand from the front of the machine for controlling the operation of said pneumatically operated means.

97. In a slug casting machine, the combination of an ejector mechanism adjustable as to blade width, a slug trimming mechanism adjustable to accommodate slugs of different thicknesses, and common means for effecting such adjustment of the two said mechanisms.

98. In a slug casting machine, the combination with an ejector mechanism comprising a main actuating slide, a series of blade sections arranged in superposed edge to edge relation, a shiftable element to connect any selected number of blade sections to the main actuating slide so as thus to vary the blade width of the ejector mechanism, and with a pair of slug trimming knives, one adjustable relatively to the other to accommodate slugs of different thicknesses and a shiftable element to effect such adjustment of the trimming knife, of common means for shifting both said elements.

99. In a slug casting machine equipped with a series of molds interchangeable as to operative position, the combination of an ejector mechanism adjustable as to blade width, a slug trimming mechanism adjustable to accommodate slugs of different thicknesses, and means actuated automatically by an interchange of molds for adjusting the ejector mechanism and the slug trimming mechanism to correspond with the slot length and slot width of the mold in use.

100. In a slug casting machine, the combination with a mold holder and a storage magazine containing a series of molds and with an ejector mechanism adjustable as to blade width as well as with a slug trimming mechanism adjustable to accommodate slugs of different thicknesses, of common means for transferring any selected mold from the storage magazine to the mold holder and for simultaneously adjusting the ejector mechanism and the slug trimming mechanism to correspond with the slot length and slot width of said selected mold.

101. A combination according to claim 78, wherein the adjustable knife is moved to an inoperative position prior to the shifting of the adjusting element to the given starting position, so as to break the engagement between these parts during the shifting of said element, and is then, after the adjusting element has been shifted from said starting position to the final position required, moved back into engagement with said element which thus determines its proper adjustment.

102. In a slug casting machine, the combination of a slug ejector, and pneumatically operated means for actuating said ejector at the proper stage in the casting cycle.

103. In a slug casting machine, the combination of a slug ejector, pneumatically operated means for actuating said ejector, and automatic means for controlling the operation of said pneumatically operated means.

104. In a slug casting machine, the combination of a slug ejector, pneumatically operated means for actuating the ejector in its advance stroke, and cam operated means for actuating the ejector in its return stroke.

105. In a slug casting machine, the combination of a slug ejector, pneumatically operated means for actuating the ejector in its advance stroke, and cam operated means for actuating the ejector in its return stroke, said cam operated means also acting to control the advance stroke of the ejector under the influence of the pneumatically operated means.

106. In a slug casting machine, the combination of a slug ejector, an air cylinder containing a piston connected to said ejector, and valve means for admitting air into the cylinder at one side of the piston in effecting the actuation of the ejector.

107. In a slug casting machine, the combina-

tion of a slug ejector, an air cylinder containing a piston connected to said ejector, and time-controlled valve means for admitting air into the cylinder at one side of the piston in effecting the actuation of the ejector.

108. In a slug casting machine wherein the mold is movable from a normal ejecting position to a casting position and return at each cycle of operation of the machine, the combination of a slug ejector operable in timed relation to said mold, and automatically controlled pneumatic means for effecting the operation of the ejector.

109. In a slug casting machine wherein the mold is movable from a normal ejecting position to a casting position and return at each cycle of operation of the machine, the combination of a slug ejector operable in timed relation to said mold, automatically controlled pneumatic means for effecting the operation of the ejector, and automatic safety means to prevent the operation of the ejector when the mold during the slug ejecting period fails to occupy its proper position.

110. In a slug casting machine wherein the mold is movable from a normal ejecting position to a casting position and return at each cycle of operation of the machine, the combination of a slug ejector operable in timed relation to said mold, automatically controlled pneumatic means for effecting the operation of the ejector, and automatic safety means to prevent the operation of the ejector, said means being rendered effective or ineffective according as the mold during the slug ejecting period stands out of or in proper ejecting position, respectively.

111. A combination according to claim 110, characterized in that the automatic safety means include an air valve operated by the mold.

112. In a slug casting machine wherein the mold after casting is moved to an ejecting position, the combination of a slug ejector operable in timed relation to the mold, and automatic safety means to prevent the operation of the ejector when the mold during the slug ejecting period fails to occupy its proper position.

113. In a slug casting machine wherein the mold after casting is moved to an ejecting position, the combination of a slug ejector operable in timed relation to the mold, and automatic safety means permitting or preventing the operation of the ejector according as the mold, during the slug ejecting period, occupies or fails to occupy its proper position.

114. In a slug casting machine wherein the mold after casting is moved to an ejecting position, the combination of a slug ejector operable in timed relation to the mold, and automatic locking means to hold the mold in its proper position during the slug ejecting period.

115. In a slug casting machine wherein the mold after casting is moved to an ejecting position, the combination of a slug ejector operable in timed relation to the mold, and locking means controlled by the operation of the ejector for holding the mold in proper position during the slug ejecting period.

116. In a slug casting machine wherein the mold after casting is moved to an ejecting position and the ejector is then operated to eject the slug therefrom, the combination of pneumatic means for effecting such movement of the mold, separate pneumatic means for effecting the slug ejecting movement of the ejector, time-controlled valves governing the operation of the two said pneumatic means, and automatic safety means

permitting or preventing the slug ejecting movement of the ejector according as the mold, during the slug ejecting period, has been moved by its pneumatic means to the proper ejecting position.

117. In a slug casting machine wherein the slug after casting is ejected from the mold and pushed between a pair of trimming knives, the combination of means for reciprocating the mold back and forth between casting and ejecting positions, a reciprocable knife wiper, and connections from the mold reciprocating means for reciprocating the knife wiper.

118. In a slug casting machine wherein the slug after casting is ejected from the mold and pushed between a pair of trimming knives, the combination of means for moving the mold back and forth between casting and ejecting positions, a reciprocable knife wiper, and connections from the mold moving means for reciprocating the knife wiper, said connections being arranged to move the knife wiper in one direction as the mold is moved from ejecting to casting position and then in the opposite direction as the mold is moved from casting to ejecting position.

119. In a slug casting machine wherein the slug after casting is ejected from the mold and pushed between a pair of trimming knives, the combination of a mold holder mounted to swing from a normal ejecting position to a horizontal casting position and return at each casting cycle of the machine, a reciprocable knife wiper, and means whereby the knife wiper is reciprocated by the swinging movements of the mold holder.

120. In a slug casting machine, the combination of a mold holder mounted to swing from a normal vertical ejecting position to a horizontal casting position and return at each casting cycle of the machine, means for effecting such swinging movements of the holder, and mold face wiping means arranged to act as the holder is swung to its horizontal casting position.

121. In a slug casting machine, the combination of a mold holder mounted to swing from a normal vertical ejecting position to a horizontal casting position and return at each casting cycle of the machine, means for effecting such swinging movements of the holder, and mold face wiping means arranged to engage both faces of the mold as the holder is swung to its horizontal casting position.

122. In a slug casting machine, the combination of a mold holder mounted to swing from a normal vertical ejecting position to a horizontal casting position and return at each casting cycle of the machine, means for effecting such swinging movements of the holder, means comprising a pair of mold face wiping devices normally located so as to permit the holder with its mold to pass freely between them, and means for moving the wiping devices into engaging relation with the mold faces as the mold holder is swung to its horizontal casting position.

123. In a slug casting machine, the combination of a mold holder mounted to swing from a normal vertical ejecting position to a horizontal casting position and return at each casting cycle of the machine, means for effecting such swinging movements of the holder, means comprising a pair of mold face wiping devices normally located so as to permit the holder with its mold to pass freely between them, means for moving the wiping devices into engaging relation with the mold faces as the mold holder is swung to its horizontal casting position, and means acting while the wiping devices are thus

engaged to move the same longitudinally of the mold.

124. In a slug casting machine, the combination of a mold holder mounted to swing from a normal vertical ejecting position to a horizontal casting position and return at each casting cycle of the machine, means for effecting such swinging movements of the holder, means comprising a pair of mold face wiping devices normally located so as to permit the holder with its mold to pass freely between them, means for moving the wiping devices into engaging relation with the mold faces as the mold holder is swung to its horizontal casting position, and means acting while the wiping devices are thus engaged to move the same longitudinally of the mold and for restoring the wiping devices to their normal positions prior to the return of the holder to its slug ejecting position.

125. In a slug casting machine, the combination of a mold holder mounted to swing from a normal vertical ejecting position to a horizontal casting position and return at each casting cycle of the machine, means for effecting such swinging movements of the holder, and mold face wiping means arranged to act as the holder is swung to its horizontal casting position, said wiping means being pivotally mounted and so located as to move longitudinally of the mold as the latter is swung to its horizontal casting position.

126. In a slug casting machine, a mold holder fixed at one end to a hollow rock shaft by which it is swung to and from casting position, in combination with cooling means for circulating water through the mold holder, and inlet and outlet water ducts connected to the cooling means and passing through said hollow rock shaft.

127. A combination according to claim 3, wherein the motion transmitting connection includes a rocker element geared to the rock shaft and movable in opposite directions in swinging the holder to and from its casting position, said holder being formed with water cooling channels extending along its opposite side walls and connected at the open end of the holder through an offset end piece with which the holder is provided.

128. A mold for use in a slug casting machine equipped with a holder having spaced side members between which the mold is located and which is open at one end for the endwise insertion and removal of the mold, said mold including spaced cap and body portions presenting each, at its outer edge, a tongue arranged to engage the holder when the mold is inserted therein and acting to transfer heat to the holder during the casting operation.

129. A mold for use in a slug casting machine and which includes a cap portion, a body portion, intermediate end liners, and a plate at each end of the mold engaging in registering recesses formed in said cap and body portions and in the adjacent end liner whereby all of said mold portions are held against relative movement in a facewise direction.

130. A mold for use in a slug casting machine equipped with a holder having spaced side members between which the mold is located and which is open at one end for the endwise insertion and removal of the mold, said mold being provided with end pieces to guide the mold during its insertion in and removal from the holder.

131. A mold for use in a slug casting machine

equipped with a holder having spaced side members between which the mold is located and which is open at one end for the endwise insertion and removal of the mold, said mold being provided at one end with means to cooperate with a locking device with which the mold holder is provided and by which the mold is locked against endwise movement out of the holder.

132. A mold for use in a slug casting machine equipped with a holder having spaced side members between which the mold is located and which is open at one end for the endwise insertion and removal of the mold, said mold being provided at one end with means to cooperate with a reciprocable slide by which the mold is inserted in and removed from the holder.

133. A mold for use in a slug casting machine equipped with a holder having spaced side members between which the mold is located and which is open at one end for the endwise insertion and removal of the mold, said mold being provided at one end with an extension piece which serves to guide the mold endwise during its insertion in and removal from the holder, and which is provided with a notch or recess for engagement with a locking latch by which the mold is locked against endwise movement out of the holder.

134. A mold for use in a slug casting machine equipped with a holder having spaced side members between which the mold is located and which is open at one end for the endwise insertion and removal of the mold, said mold being provided at one end with an extension piece which serves to guide the mold endwise during its insertion in and removal from the holder, and which is formed with a hook-shaped projection to cooperate with a similar shaped projection of a reciprocable slide by which the mold is inserted in and removed from the holder.

135. In a slug casting machine, the combination of a mold holder mounted to swing from a normal vertical ejecting position to a horizontal casting position and return at each casting cycle of the machine, means for effecting such swinging movements of the holder, means for moving the holder while in horizontal casting position forwardly and backwardly to carry the mold into and out of contact with a composed line before and after casting, respectively, a horizontally movable metal pot likewise movable forwardly and backwardly while the holder is in horizontal casting position into and out of contact with the mold before and after casting, respectively, and means for effecting such movements of the metal pot, said means including pressure applying devices which bring about the proper lockup between the composed line, mold and metal pot during casting.

136. In or for a slug casting machine wherein a mold holder is swung to and from casting position, a stationary knife to trim the base of the slug as the holder is swung from casting position after the casting operation, said knife being adjustable edgewise upon a pair of inclined supports whereby the cutting edge of the knife may be located in proper trimming relation to the base of the mold.

137. In a slug casting machine, the combination of a mold holder mounted to swing from a normal vertical ejecting position to a horizontal casting position and return at each casting cycle of the machine, a slug ejector operable upon the return of the holder to its normal position to push the slug out of the mold and through a pair of slug

trimming knives which trim the faces of the slug, said ejector being adjustable as to width to correspond with the slot length of the mold in use, and said trimming knives being adjustable as to spacing to correspond with the slot width of the mold in use, a mold magazine located immediately below the mold holder and containing a series of molds in individual pockets, said mold magazine being adjustable to align any selected pocket with the mold holder so that the mold therein may be transferred into and out of the mold holder, transfer means movable from one position to a second position to transfer a mold from the magazine to the holder, and back to its original position to return the mold from the holder to its pocket in the magazine, a device for locking the transfer means in said second position when the mold is in the holder, devices for locking the mold in the holder, pneumatic means for moving the transfer means between said two positions, and mechanism including connections and a common control located at the front of the machine for releasing the transfer slide locking device, releasing the mold locking devices, operating the transfer means to restore the mold to the magazine, and adjusting the ejector blade width and the trimming knife spacing to a neutral setting, and said mechanism likewise serving, after the mold magazine has been adjusted to bring a different mold into the transfer position, to operate the transfer means to move the selected mold into the holder, render the mold locking devices active, the transfer slide locking device active, and to adjust the ejector blade width and the trimming knife spacing respectively, in accordance with the slot length and width of the selected mold, the connections included in said mechanism being such as not to interfere with the swinging movement of the mold during normal machine operation.

138. In or for a slug casting machine, an ejector mechanism operable to push a slug out of the mold and which includes a force transmitting connection arranged to exert a force upon the slug varying in magnitude throughout the ejecting operation.

139. In or for a slug casting machine, an ejector mechanism operable to push a slug out of the mold and which includes a force transmitting connection arranged to exert a force upon the slug varying in magnitude throughout the ejecting operation, said force being greatest at the beginning of the ejecting operation when the slug breaks from the mold.

140. In or for a slug casting machine, an ejector mechanism operable to push a slug out of the mold and which includes a force transmitting connection arranged to exert a force upon the slug varying in magnitude throughout the ejecting operation, said force being greatest at the beginning of the ejecting operation when the slug breaks from the mold and thereafter diminishing as the operation proceeds.

141. In or for a slug casting machine, an ejector mechanism operable to push a slug out of the mold and which includes a toggle device connected so as to exert a maximum force upon the slug at the beginning of the ejecting operation and thereafter a gradually diminishing force as the ejecting operation proceeds.

142. A combination according to claim 115, wherein the locking means in turn prevents operation of the slug ejector in the event the mold is not located in proper position for slug ejection.

143. In a slug casting machine, the combination of a mold holder, a storage magazine containing a series of molds and movable to bring any selected mold into alignment with the holder, power operated means controlled from the front of the machine for transferring the selected mold from the magazine to the holder and vice versa, and safety devices for preventing the inauguration of the casting cycle in the event the selected mold is not properly located in the holder.

144. In a slug casting machine, the combination of a mold holder open at its end to permit the endwise insertion and removal of a mold, a latch member cooperating with means on the mold for locking the mold against endwise movement in the holder, means controlled from the front of the machine for rendering the latch member inoperative or operative depending upon whether a mold is to be removed from or has been inserted in the holder, and safety devices for preventing the inauguration of a casting cycle in the event the inserted mold has not been properly located in the holder.

145. In a slug casting machine, the combination of a mold holder open at the end to permit the endwise insertion and removal of a mold, a storage magazine containing a series of molds and movable to bring any selected mold into alignment with the holder, power operated means for transferring the selected mold from the magazine to the holder and vice versa, a latch member cooperating with means on the active mold to lock the same against endwise movement in the holder, common control means located at the front of the machine for rendering the latch member inoperative and for causing the power operated means to transfer the mold in the holder to the magazine and after a selected mold has been brought into alignment with the holder, for causing the power operated means to transfer the selected mold into the holder and for rendering the latch member operative, and safety devices associated with said common control means for preventing the inauguration of a casting cycle in the event the selected mold is not adjusted to its proper place in the mold holder.

146. In a slug casting machine wherein the mold after casting is moved to an ejecting position, the combination of a slug ejector operable in timed relation with the normal movement of the mold and under the control of devices for regulating its speed of operation, and supplementary means for controlling the speed of operation of the slug ejector in the event the movement of the mold to slug ejecting position departs from normal.

147. In a slug casting machine wherein the mold after casting is moved to an ejecting position, the combination of a slug ejector, pneumatic means for operating the ejector in timed relation with the normal movement of the mold and under the control of cam means for regulating its speed of operation, and a dash pot associated with said pneumatic means for controlling the speed of operation of the slug ejector in the event said cam means is unable to function as a result of a departure of the mold from its normal movement to slug ejecting position.

148. A combination according to claim 79, wherein the adjustable knife is moved to an inoperative position prior to the shifting of the adjusting element to the given starting position, so as to break the engagement between these parts during the shifting of said element, and is then, 70 75

5 after the adjusting element has been shifted from said starting position to the final position required, moved back into engagement with said element which thus determines its proper adjustment.

149. In a slug casting machine, the combination of a mold holder, a storage magazine containing a series of molds and movable to bring any selected mold into alignment with the holder, means for transferring a mold located in the holder into its proper position in the magazine and a newly selected mold from the magazine into the holder, releasable locking means carried by the mold holder for confining a mold therein, a pair of slug trimming knives, one adjustable relatively to the other to accommodate slugs of different thicknesses, a shiftable element to effect such adjustment of the trimming knife, means operable as a mold is transferred from the holder into the magazine to shift said adjusting element to a given starting position and, as a newly selected mold is transferred from the magazine to the holder, to shift said adjusting element to the final position required, and common means operable from the front of the machine for rendering the mold locking means inoperative and for shifting the adjustable knife to an inoperative position preparatory to the selection of a new mold.

150. In a slug casting machine, the combination of a mold holder, a storage magazine containing a series of molds and movable to bring any selected mold into alignment with the holder, means for transferring a mold located in the holder into its proper position in the magazine and a newly selected mold from the magazine into the holder, releasable locking means carried by the mold holder for confining a mold therein, a pair of slug trimming knives, one adjustable relatively to the other to accommodate slugs of different thicknesses, a shiftable element to effect such adjustment of the trimming knife, means operable as a mold is transferred from the holder into the magazine to shift said adjusting element to a given starting position and, as a newly selected mold is transferred from the magazine to the holder, to shift said adjusting element to the final position required, common means operable from the front of the machine for rendering the mold locking means inoperative and for shifting the adjustable knife to an inoperative position preparatory to the selection of a new mold, said common means serving also to render operative the mold locking means and move the adjustable knife to an operative position as determined by the final adjusted position of its associated shiftable element after the newly selected mold has been transferred to the holder.

151. In a slug casting machine, the combination of a mold holder, a storage magazine containing a series of molds and movable to bring any selected mold into alignment with the holder, means for transferring a mold located in the holder into its proper position in the magazine and a newly selected mold from the magazine into the holder, releasable locking means carried by the mold holder for confining a mold therein, a pair of slug trimming knives, one adjustable relatively to the other to accommodate slugs of different thicknesses, a shiftable element to effect such adjustment of the trimming knife, means operable as a mold is transferred from the holder into the magazine to shift said adjusting element to a given starting position and, as a newly selected mold is transferred from the magazine to

the holder, to shift said adjusting element to the final position required, and common means operable from the front of the machine, for rendering the mold locking means inoperative, for shifting the adjustable knife to an inoperative position preparatory to the selection of a new mold and for controlling the operation of the transfer means in moving the mold from the holder into the magazine.

152. In a slug casting machine, the combination of a mold holder, a storage magazine containing a series of molds and movable to bring any selected mold into alignment with the holder, means for transferring a mold located in the holder into its proper position in the magazine and a newly selected mold from the magazine into the holder, releasable locking means carried by the mold holder for confining a mold therein, a pair of slug trimming knives, one adjustable relatively to the other to accommodate slugs of different thicknesses, a shiftable element to effect such adjustment of the trimming knife, means operable as a mold is transferred from the holder into the magazine to shift said adjusting element to a given starting position and, as a newly selected mold is transferred from the magazine to the holder, to shift said adjusting element to the final position required, common means operable from the front of the machine, for rendering the mold locking means inoperative, for shifting the adjustable knife to an inoperative position preparatory to the selection of a new mold and for controlling the operation of the transfer means in moving the mold from the holder into the magazine, said common means serving also to control the subsequent operation of the transfer means in moving a newly selected mold from the magazine into the holder and to render operative the mold locking means and to move the adjustable knife to an operative position as determined by the final adjusted position of its associated shiftable element.

153. In a slug casting machine, the combination of a mold holder pivotally mounted at one end to swing upwardly from a normal vertical ejecting position to a horizontal casting position and return at each casting cycle of the machine, said holder being open at its free end to permit the endwise insertion and removal of a mold, and a storage magazine disposed below the level of the mold holder and containing a series of vertically disposed molds arranged one behind another in a fore-and-aft direction, said magazine being slidable forwardly and backwardly to bring any selected mold into vertical alignment with the overlying holder when the latter occupies its normal position, a vertically movable slide supported beneath the magazine and arranged in line with the holder, said slide being operable to lift the selected mold from the magazine into the holder as well as to lower it from the holder into the magazine, a lock for maintaining the slide in its raised position, releasable locking means carried by the mold holder for confining the mold therein, a pair of slug trimming knives, one adjustable relatively to the other to accommodate slugs of different thicknesses, a shiftable element to effect such adjustment of the trim-

ming knife, means operable as a mold is transferred from the holder into the magazine to shift said adjusting element to a given starting position and, as a newly selected mold is transferred from the magazine into the holder, to shift said adjusting element to the final position required, and common means, operable from the front of the machine for rendering the slide lock and the mold locking means inoperative, for shifting the adjustable knife to an inoperative position preparatory to the selection of a new mold and for controlling the operation of the transfer means in lowering the mold from the holder into the magazine.

154. In a slug casting machine, the combination of a mold holder pivotally mounted at one end to swing upwardly from a normal vertical ejecting position to a horizontal casting position and return at each casting cycle of the machine, said holder being open at its free end to permit the endwise insertion and removal of a mold, and a storage magazine disposed below the level of the mold holder and containing a series of vertically disposed molds arranged one behind another in a fore-and-aft direction, said magazine being slidable forwardly and backwardly to bring any selected mold into vertical alignment with the overlying holder when the latter occupies its normal position, a vertically movable slide supported beneath the magazine and arranged in line with the holder, said slide being operable to lift the selected mold from the magazine into the holder as well as to lower it from the holder into the magazine, a lock for maintaining the slide in its raised position, releasable locking means carried by the mold holder for confining the mold therein, a pair of slug trimming knives, one adjustable relatively to the other to accommodate slugs of different thicknesses, a shiftable element to effect such adjustment of the trimming knife, means operable as a mold is transferred from the holder into the magazine to shift said adjusting element to a given starting position and, as a newly selected mold is transferred from the magazine into the holder, to shift said adjusting element to the final position required, and common means operable from the front of the machine for rendering the slide lock and the mold locking means inoperative, for shifting the adjustable knife to an inoperative position preparatory to the selection of a new mold and for controlling the operation of the transfer means in lowering the mold from the holder into the magazine, said common means serving also to control the subsequent operation of the transfer slide in lifting a newly selected mold from the magazine into the holder, to move the adjustable knife to an operative position as determined by the final adjusting position of its associated shiftable element and to render operative the slide lock and the mold locking means.

155. In a slug casting machine, the combination of a mold holder mounted to swing from a normal vertical ejecting position to a horizontal casting position and return at each casting cycle of the machine, and means for effecting such swinging movements of the holder.

JAMES C. PLASTARAS.
